UNITED STATES PATENT OFFICE

2,033,248

SHOE MACHINE

Robert H. Lawson, Beverly, Mass., assignor to
United Shoe Machinery Corporation, Paterson,
N. J., a corporation of New Jersey

Application May 21, 1931, Serial No. 538,963

244 Claims. (Cl. 1—32)

My invention relates to shoe machines, and particularly to those employed for operating upon the heel-portions of shoes, the embodiment of the invention herein disclosed being arranged 5 to prick in heel-bases nail-receiving openings, attach such bases to shoes by nails driven in the pricked openings, and to further nail lifts of rubber or other material upon the attached bases. It includes certain subject-matter in 10 common with the application for improvements in Machines for operating upon shoes, filed in my name in the United States Patent Office on February 4, 1926, with the Serial No. 86,078, and which, on January 5, 1932, became Patent No. 15 1,839,852.

An object of the invention is to provide for rapid and effective operation of an apparatus of the character above indicated, the pricking, nailing or other operations going on while the 20 operator is removing work which has been previously operated upon and is supplying other work. For the attainment of this object, there are employed a plurality of operating mechanisms, as those for pricking, base-nailing and 25 lift-nailing, said mechanisms being movable to an operating position common to all and there movable to perform their operations, and a plurality of work-supports or jacks movable to receive the action of the mechanisms at such common 30 position, the supports and mechanisms being moved to and from the common operating position in definite time-relation to each other, the work being retained by each support at such position to receive the successive action of the 35 operating mechanisms. The operating mechanisms are shown as mounted upon a rotatable turret or support, while there are plural work-supports, preferably two in number, which successively present the work to the operating mechanisms, the operator unjacking and jacking shoes 40 at the same time the operating cycle is being performed upon a previously jacked shoe by the plural mechanisms automatically moved into position and actuated. At the operating position, 45 each mechanism comes under the influence of an actuating mechanism which is common to all. I also preferably employ pressure mechanism which moves toward and holds the work-supports in operating relation to the turret-borne 50 mechanisms, and which is common to all said work-supports. The actuating and pressure mechanisms are of such a character and so mounted as to effectually apply their forces and resist those to which they are subjected. Among 55 the features which contribute to the effectiveness

of my improved machine are the manner of mounting, positioning and actuating the work-supports or jacks; the automatic initiation of the operating cycle under the influence of a work-support; the character and manner of control of the pressure mechanism, including a diminution of pressure when lifts are being attached; the construction of the turret and the mounting of the operating mechanism thereon; the adapting of the pricking mechanism to insert simultaneously with the pricking operation one or more preliminary base-securing nails; the arrangement of the operating mechanisms in independently movable sections which may be positioned by contact with the work; the organization of the common actuating mechanism for the operating mechanisms; the manner of locking the plural sections of the various operating mechanisms; and the means for introducing such work-pieces as the lifts into attaching 10 position.

A further object of the invention is to so supply nails to the nailing mechanisms that the change from one size of nail to another is facilitated, and, if desired, nails of different sizes may be delivered from a single holding device for one 15 heeling operation. To this end, I combine with a plurality of nailing mechanisms, which may be any or all of the preliminary base-nailing, final base-nailing and lift-nailing organizations previously 20 mentioned, a unitary holder, as a block provided with nail-holding openings, and means arranged to deliver nails from the holder to plural nailing mechanisms. The delivery is from certain holding openings to one nailing mechanism, 25 and from other openings to another mechanism. The blocks may be loaded with nails for the heeling of a particular lot of shoes, and for a different lot it is only necessary to supply the apparatus with a block holding the kind or size of nails 30 which should be employed. Because of the delivery from particular block-openings to particular nailing mechanisms, a single block may supply nails of one character to the pricking and base-nailing mechanisms and of a different character to the lift-nailing mechanism. I prefer to 35 arrange the nail-holding openings in a series of sets, each set containing the nails for a single heeling operation and there being in the series enough sets, for example, to supply nails for the 40 heeling of a case of shoes. There are connections between the holder and nailing mechanisms whereby different mechanisms receive nails from different openings of each set, and there is 45 means for moving the holder as the nails in differ- 50 55

ent sets of openings of the series are successively delivered, first for work upon one support or jack and then for that upon another. To increase the number of loads of nails which may be used, 5 without attention by the operator, there is associated with the nail-supplying mechanism a container or magazine for a plurality of holding devices, together with means for transferring them therefrom for use, and means for presenting them successively in the container for transfer. 10 This transfer occurs after a predetermined number of operations of the nailing mechanism, indicating that the nails from the preceding holding device have become exhausted. Features of 15 the nail-supplying or distributing mechanism involve the arrangement of the magazine and the transfer of the blocks or holding devices from it to feeding means, preferably cooperating with a stationary support or table along which the blocks 20 are advanced in the delivery of the contained nails; the manner of stripping from each block its nail-retaining slide or shutter to prevent interference of the freed nails with a delivering device which determines the particular nailing mechanisms 25 to which they pass; the feeding mechanism which advances the nail-holding blocks step by step for delivery; the retaining means for the feeding mechanism and its release at the completion of the feed of each block; and the 30 arrangement and actuation of the delivering device to effect the selective distribution of the sets of nails to the plural nailing mechanisms.

In the accompanying drawings,

Fig. 17 (Sheet 5), a vertical sectional detail on the line XVII—XVII of Fig. 13.

As to the general plan of operation of the machine, the shoes to be heeled are placed alternately upon oscillatory jacks J and j. Each jack with the applied shoe S is carried, first manually as advanced by the operator and then automatically under the power of the machine, from the

work-receiving position to an operating position, the former positions of both jacks being in close proximity to each other and the latter common to the two jacks. When the operations are being performed upon the work carried by the thus-advanced jack, the operator is supplying the companion jack with a shoe, which is similarly moved into operating position when the jack with the heeled shoe is automatically thrown out by the machine. The work in the operating position 10 is acted upon successively, in definite time-relation to its introduction and ejection upon the jacks, by three mechanisms A, B and C (Fig. 4) spaced uniformly about a supporting turret T rotatable about a vertical axis. Each of these operating mechanisms may be of the general character of that disclosed in Letters Patent of the United States No. 1,686,821, granted October 9, 1928, on an application filed in my name, having independent movable sections adjusting themselves to the contour of the article upon which they act, each section either pricking nail-receiving openings or inserting nails in the work. The mechanism A (Fig. 7) is organized to first prick eight holes p in a heel-base H which the 25 operator has applied to the heel-seat of the jacked shoe before movement toward the operating position. At the same time with the pricking of the openings, two nails N are driven at a to secure the base until the mechanism B has 30 operated upon it. The location of the pricked openings and the points of insertion of the nails are as shown in Fig. 12 of the drawings. Then the turret is turned through 120° and the mechanism B (Fig. 10) arrives at the operating position, its sections driving eight nails at b in the pricked holes p. These nails effect the permanent attachment of the base to the heel-seat of the shoe. Following this, the mechanism C comes 35 into position as the turret again turns through 120°, and a top lift h, which may be of rubber, is automatically carried over the base by a holder D, in which it has been placed by the operator, and is secured to said base by six nails driven at c. This completes the heeling of the shoe, and its 45 jack is swung out to the work-receiving position, while the turret rotates through the final 120° of the cycle to present mechanism A at the operating position. At said operating position is pressure mechanism E (Fig. 3) engaging the jack 50 which is at the time active and serving to clamp the work successively against the three mechanisms A, B and C to resist the pricking and nail-inserting forces. Similarly, the pricking and driving instrumentalities are successively reciprocated in their mechanisms A, B and C by actuating mechanism F (Figs. 2 and 7) common to all and into engagement with which the rotation of the turret T successively carries them. Nails are automatically supplied to the operating mechanisms by a distributing mechanism 60 G (Figs. 13 to 17). This mechanism G delivers the three groups of nails for insertion at a, b and c from sets of openings extending transversely of holder-blocks g, there being a series of these sets 65 of openings extending longitudinally of each block, as in United States Patent No. 1,325,751, Pope, December 23, 1919. A supply of the blocks g to the distributor is automatically maintained from a magazine M as each block is emptied of 70 its nails.

Considering now in detail the structure of the machine, it has a main frame 20, which supports and to a considerable extent encloses the elements. The turret T rotates within this en- 75

closure, and access to its mechanisms A, B and C by the jacks J and *j* is given by an opening 22 at the front. As is best seen in Figs. 1, 3 and 6 of the drawings, there are carried in lugs 24 at 5 opposite sides of the opening 22 vertical pivot- rods 26, about which oscillate hollow jack-supporting arms 28, 28. A description of the arrangement of one of the jacks and its mounting will, in the main, serve for both. In the outer 10 extremity of each arm is a vertical bore, in which is rotatable a cylindrical carrier member 30 supported by a flange 32 resting upon the arm. At the top of this carrier member are ways 33 to receive a jack, as J, which will support an unlasted 15 shoe S for the heeling operation. As illustrated, this jack is arranged for cooperation with a shoe in the heel-seat-end of the bottom of which are two positioning openings. It is therefore provided with spaced pins 34, 34 (Fig. 2), shown as 20 mounted to yield vertically. These pins receive the openings in the shoes and locate them in the correct relation to the mechanisms which are to perform the heeling operations. The pins are also sufficiently long to enter openings in each 25 base H and lift *h* to fix the location of these relatively to the shoe and to the operating mechanisms. To maintain the jack in the same angular relation about its vertical axis so it may be convenient for the operator to apply and remove 30 the work in the outward position and so said work will be properly presented to the operating mechanisms, the member 30 has formed in its periphery a gear-segment 36, the teeth of which are elongated vertically. The segment 36 is engaged by a gear-segment 38 upon one arm of a bell-crank lever 40 fulcrumed within the arm 28. A chain of connections, made up of a link 42 (Fig. 1), bell-crank lever 44 and a link 46, joins the lever 40 through the arm 28 to a projection 40 formed upon the upper lug 24. As a result 45 of these connections, as each arm 28 is swung from work-receiving to operating position and reversely, the jack-carrier 30 is rotated in its arm, as well as revolved thereby, to maintain the jack in the same angular relation, this being parallel to the longitudinal axis of the machine.

To produce automatic movement of the jacks into and out of operating position, the pivot-rod 26 of the arm 28 of jack J has fixed to its lower portion an arm 50 extending into the frame and united by a link 52 to a lever 54 fulcrumed near the rear of said frame. The pivot-pin of the jack *j* has secured at its upper portion an arm 56 expanded laterally to sector-form, and this, similarly 55 to the associated arm 28, is joined by a link 52 to a lever 54. These lower and upper levers 54 have their inner extremities lying in substantially the same vertical plane, and each has mounted upon it a roll 58. The rolls belonging to the jacks J and *j* are received at points 180° apart by a cam-groove 60 in the periphery of a disk 62 rotatable about a horizontal shaft 64 extending longitudinally of the machine. The cam-disk is driven from a motor 66 through reduction-gearing 68, an 65 elongated pinion 70 secured to the shaft 64, a gear 72 fast upon a lower horizontal shaft 74, a pinion 76 fixed upon said shaft, and a gear 78 formed with the disk. The contour of the groove 60 is such that, at the beginning of the operating cycle, the roll of the chain of connections from one of the jacks is in a portion 80 of the groove parallel to the axis. At this time, this jack may be swung by the operator from the work-receiving position toward the operating position. 70 Upon starting the machine, the remainder of the 75

cam-groove 60 for 180° completes the inward movement of the jack and locks it in position for registration with the operating mechanisms A, B and C for the performance of the operations upon a jacked shoe. Prior to this, the companion jack, which has been locked in operating position by the cam, is released, at a point diametrically opposite the portion 80 and is moved out of operating position under the influence of the remaining 180° of the cam. It is thus made ready to receive 10 the next shoe to be heeled while the preceding shoe is being operated upon. Near the top of the pivot-rod of jack J is attached a sector-plate 73, similar in character to the arm or plate 56. In each of the plates 56 and 73 are two depressions 15 75. With these depressions and with an intermediate arcuate edge of each plate contacts a roll 77 upon the forward extremity of a latching lever 79 fulcrumed on the frame and urged toward the plate by a spring 81. The corresponding roll 77 rests within one or the other of the sector-plate-depressions, thus determining the exact position of the jack at each of its extremes of movement. When one of the arms 28 is actuated, either by the operator or by the machine, the edge of the sector rides beneath the roll, the lever 79 yielding to permit this. 20 25

As either jack approaches the inner operating position as a result of its manual actuation, the rear of its arm 28 contacts with the inner rounded 30 end of a lever 82 fulcrumed horizontally upon the frame. This lever is joined by a link 84 to a lever system 86 (Fig. 2), which produces the engagement of a single-rotation clutch 88 to connect the reduction-gearing 68 of the driving 35 mechanism for the machine to the shaft 64, and thus start the operating cycle, which includes the automatic movement of the jacks just described. The cycle is terminated by a lever 90 actuated by 40 a cam-surface upon the rear face of the gear 78 and contacting with a collar 92 upon the link 84 to disengage the clutch 88.

There is to be applied to the jacked work, during the operations of each of the mechanisms A, B and C upon it, first a preliminary or measuring 45 pressure, which establishes contact of the work with the particular one of the three mechanisms with which it co-operates, and then a final or clamping pressure, which prepares the work to resist the operating forces. This is accomplished 50 by the mechanism E. As best illustrated in Figs. 2 and 3, there is located below the inward position which the jack assumes a slide 94 arranged to reciprocate vertically in the frame. At the top of this slide, extending from front to rear, are 55 ways 96 to receive correspondingly arranged tongues 98 at the bottom of each jack-carrier 30 (Fig. 6). Thus, in operating position, the jack and slide are united for movement together. The slide 94 is provided with an axial threaded portion, in which is a screw 100 rising from and rotatable upon a lower slide 102. The screw is turned through sprocket-gearing 104 and a friction device 106 from a vertical shaft 103, an idle sprocket 110 (Fig. 1) directing the chain of the 60 gearing in the proper path. Near the bottom of the shaft 103 is a pinion 112, with which meshes a gear-segment 114 upon a lever 116 fulcrumed at 118 for horizontal movement. A roll 120 upon this lever lies within a cam-groove 122 in the 65 periphery of a disk 124 secured to the shaft 74. The cam-groove 122 is so formed and timed that, through the rotation of the screw 100, it successively raises and lowers the jack acted upon by the slide 94 three times during each operating 70 75

cycle, thus causing engagement of the work with each of the mechanisms A, B and C. To insure full contact of the work with these mechanisms, the extent of vertical travel imparted to the jack may be in excess of what is actually required, the friction at 106 slipping to compensate for this.

To allow final pressure to be applied to the work, the slide 102 has fulcrumed upon it at 130 a cam-lever 132. The lever supports the slide by contact with an abutment-roll 134 rotatable upon a normally stationary slide 136 movable vertically in the frame below the slide 102. A link 138 unites the lever 132 to a head 140 adjustable in position upon a rod 142 guided for vertical movement axially of the turret T and employed to actuate all the mechanisms A, B and C, as will later appear. Downward movement is imparted to the head 140 and rod 142 through a chain of elements including double links 144, an arm 146 of a lever 147 turning about a horizontal spindle 148 supported near the bottom of the frame, a parallel arm 150 of the lever and a roll 152 upon the latter arm, which roll operates in contact with the periphery of an open cam 154 secured to the shaft 74. The head and rod are returned by engagement of a roll 156 upon the arm 150 with a cam-groove 158 in one face of the gear 72. After preliminary pressure has been applied to the work through the screw 100, to bring the active jack into co-operation with the particular operating mechanism with which it is at the time associated, the rocking of the lever 132 against the abutment-roll 134 upon the descent of the rod 142, raises the slide 102, the screw 100, the slide 94, the carrier 30 and the jack to give the final pressure. This having occurred, descent of the parts to their normal relation is assured by a lever 160 (Fig. 2) fulcrumed upon the frame and bearing at its forward extremity upon the upper side of the fulcrum member 139, and at its opposite end having a slotted connection at 162 with the head 140. Upward travel of the rod 142 forces the lever 160 against the member 138 to positively lower the slide 102 and the connected elements, including the active jack.

Lifts which are attached by the mechanism C may be of such yieldable material as rubber. This would be deformed by a clamping pressure corresponding in magnitude to that applied to the leather base. I therefore include in the machine means for decreasing to a considerable extent the final pressure placed upon the lift and base at the mechanism C from that which is made effective at the mechanisms A and B. The slide 136 carrying the abutment-roll 134 rests at its lower end upon a wedge member 170 arranged to reciprocate horizontally at the bottom of the frame. Formed upon the extended shank of the wedge is a rack 172, with which meshes a gear-segment 174 upon one arm of a bell-crank lever 176 fulcrumed above the wedge member. A link 178 unites the lever 176 to a lever 180 pivoted above it upon the frame. This connection is by a slot and screw 182, to permit variation in the throw imparted to the lever 176, and thus the travel of the wedge member 170. A roll 184 upon the lever 180 enters a cam-groove 186 surrounding a depending hub-portion 188 of the turret T. The contour of this cam-groove may be such that, following the operation of the base-nailing mechanism E, the wedge member 170 is slid to the right (Fig. 2) by its connections, so the slide 136 and abutment-roll 134 are lowered to decrease the amount which the cam-lever 132 raises

the jack-actuating slide 94. The pressure upon the work is thus reduced.

The turret T upon which the operating mechanisms A, B and C are borne, has a bearing, by means of its hub 188, in a vertical standard 190 formed in the frame. Extending axially through the hub and standard is the actuating rod 142. The weight of the turret is received by a ball-bearing 192 at the top of the standard. Secured at the upper portion of the turret is a horizontal circular plate 194, about which groups of oscillatory sections x, y and z included in the operating mechanisms A, B and C, respectively, are equally spaced, while arranged to reciprocate in the turret above this plate are three actuating plungers 196 for the mechanisms. Each of these plungers is guided in a tubular upward extension 195 from the plate 194 (Figs. 7, 13 and 14). Below this plate, a plate 198 is secured to the turret-hub for the support of pressure-springs and locking mechanisms for the sections. The outer edge of the plate 194 runs in close proximity to a cap-piece 197, strongly secured to the frame 29 and overhanging said plate. Upon application of operating pressure at any one of the mechanisms A, B and C, contact between the plate and cap-piece resists upward displacement of the turret. To rotate the turret in successive steps of 120° and to lock it at the termination of each step in co-operation with the jack J or j which may be at the time presenting a shoe for heeling, there may be utilized mechanism of the shifting-worm type, of the character of that disclosed in Letters Patent of the United States No. 1,779,510, Ray, October 28, 1930. The worm and worm-wheel appear at 200 and 202, respectively (Figs. 1 and 2), the former being loose upon a horizontal shaft 204 and the latter fast upon the turret-hub 188. The worm is rotated by an attached gear 206 meshing with the elongated pinion 70, and is reciprocated to correctly time the periods of rotation and rest of the turret by a cam-groove 208 formed in an extension of the worm and engaged by a fixed projection 210.

Of the operating mechanisms, considering first that for pricking and temporarily attaching a heel-base H which has been placed by the operator upon the pins 34 rising through the heel-seat openings of a jacked shoe S, there is secured to the plate 194 a depending abutment-post 220 (Figs. 4 and 7). This post is so situated in the operating position of the mechanism A as to be vertically aligned with the central forward portion of the heel-seat-end of the base and to a considerable extent receive the pressure created by the mechanism E. In this post are two vertical passage 222, in which reciprocate nail-drivers 224 fixed in the plunger 196 of this mechanism. Nails N are delivered to the passages, by way of branch-passages 225 through flexible tubes 226 and vertical passages 227 through the corresponding extension 197 of the turret (Figs. 13 and 14), from the distributing mechanism G, presently to be described. The nails may be retained temporarily in each passage, to receive the action of the driver, by an oscillatory abutment or stop 228 (Fig. 11). The stop turns about a pin 230 in a recess at the outer side of the passage, and has a peripheral wall 232 movable by a spring 234 seated in the section-recess to normally close the passage 222 below the connection therewith of the passage 225. Initially, each driver is elevated, and a nail may be delivered from the distributor for support by the stop. In its downward inserting

movement, the driver, by engagement of its end with the surface 232 of the abutment, rocks this anti-clockwise about its support, freeing the passage 222 so the driver carries the nail before it and effects its insertion in the work. The opening at the end of the passage 225 is now closed by an arcuate peripheral surface 238 of the abutment intersecting the wall 232, and on which is supported the nail next delivered from the distributor G. When the driver rises, the spring 234 rotates the stop clockwise, releasing the nail which has been resting at 238, and retaining it at 232, awaiting the next descent of the driver. The two nails thus driven by the mechanism A 10 through the passages 222 secure the base H until it receives its full complement of attaching nails. At the sides and rear of the post 220 are six pricking sections x arranged in symmetrical pairs. In each section of the forward pair are shown two awl-passages 240, while each of the associated sections has one passage 242. Each section is pivoted at 244 upon a lug depending from the under side of the plate 194, and is urged normally inward toward the post by a plunger 245 15 guided for horizontal movement in a casing 246 attached to the upper face of the plate 193. Each plunger receives the force of a spring 248 interposed between it and an abutment 250 rising from the plate. Projecting downwardly from the lower end of each section is a gage member 252 provided at its inner edge with an upwardly and inwardly inclined surface 254 leading to a vertical gage-surface 256. The normal relation of the sections x is such that the surfaces 256 20 are sufficiently close to one another to adapt them to engage the outer peripheral edge of the smallest heel-base to be attached. The operator, in supplying a base for nailing, places this upon the pins 34 of the jack which are projecting through the heel-seat of the shoe. Then, when the jack is raised by the pressure mechanism, the edges of the base contact with the surfaces 254 of the sections, pressing these apart against their springs 248. At the end of the upward 25 movement, or when the tread-end of the base engages the lower extremity of the post 220, the surfaces 256 will be in contact with the periphery of the base, thus locating all the sections for the insertion of the nails at predetermined 30 points.

Movable longitudinally of each passage 240 and 242 is an awl 260 pivotally joined at 262 to a link 264, the link being pivoted at 266 to the lower end of the plunger 196. The plunger is reciprocated in the turret to cause the drivers 224 to insert the initial base-securing nails, and the awls 260 to prick openings to receive the base-attaching nails driven by mechanism B, by the following connections F, which also serve to actuate mechanisms B and C. Referring to Fig. 2, a lever 270, extending horizontally above the frame 20, is fulcrumed upon said frame through a link 272. Near the forward extremity of the lever is articulated the actuating rod 142 reciprocated, as already described, by the cams 154 and 158. To the end of the lever beyond the rod-connection is pivoted at 274 a bell-crank lever 276, and to the lower arm of this lever is pivotally joined at 278 a connecting member 280 having horizontal extensions or projecting portions 282. As the turret T rotates through its three steps, the member 280 is successively received by ways 284 (Fig. 7) formed in the upper portion of the plungers 196 of the mechanisms A, B and C, and these plungers are caused by the oscillation of

the lever 270, under the control of its cams, to impart to the awls and drivers their operating strokes. Each plunger 196 is held in its normal elevated position, where it is left by the lever 270 after the completion of an operation, by a spring-actuated latch 286 movable in the turret with its conical end entering a corresponding depression in the plunger. The form of the latch-end permits the plunger to free itself when force is applied by the lever 270. In a like manner, the connecting member 280 is held normally in position to receive the ways 284 by latches 288 and 290 (Fig. 8), movable, respectively, in the lever 270 and in the connecting member 280 and entering depressions in the opposite arms 15 of the lever 270. The engaged elements are freed by the yield of these latches against their springs, to permit the actuating stroke of the lever 270. 10

To guard against displacement of the sections x under the influence of the operating forces, I associate with them locking means. This may be seen in Figs. 4, 5 and 7. Extending inwardly from each plunger 196 through a slot in the turret between each pair of sections x is a bracket 296, in which and in the turret below it is guided 25 a vertical pressure-rod 298 provided with a pivoted end-portion 300. The rod is drawn positively up when the plunger 196 rises by the engagement with its bracket of nuts threaded upon its upper end, and is forced yieldably down, upon 30 the descent of the plunger, by a spring 302 surrounding the rod and interposed between its end-portion and the turret. At opposite sides of the rod-portion 300 are vertical slots 304, the inner walls of which taper or diverge upwardly (Fig. 5). 35 With rounded ends lying in these slots and opposite ends contacting with plungers 245 are locking members 306. These locking members lie in slots in a guide member 308 held in the casing 246, there being some clearance between the 40 members 306 and the walls of the slots. Springs 310 hold the locking members yieldably at one side of the slots. When a plunger 196 descends to perform the pricking or nailing operations, the diverging walls of the slots 304, wedging between 45 the ends of the members 306, force these apart and against the plungers 245, securing the latter and the sections with which they contact against outward movement. Elevation of the plunger 196 releases the locking members and frees the 50 sections.

After the mechanism A has operated, the turret rotates a step, and mechanism B comes into co-operation with the work upon the jack. This mechanism may be seen in Figs. 4 and 10. Its 55 post 316 is imperforate, serving only to receive the clamping pressure of the central portion of the heel-base H. About it are arranged pairs of sections y, the same as to their general character, support and locking means as the sections x, save here all operate to insert the base-attaching nails, eight in number, in the openings pricked by the mechanism A. Consequently, to all their driver-passages 222, nails are delivered under the control of the retaining members 228, 60 and in each passage a driver 318 operates. The plunger 196 of the drivers engages the common connecting member 280 of the actuating lever 270, as has already been described. 65

As to the mechanism C, there are preferably 70 inserted by it six nails for attaching the lift h to the base H. One nail is driven near the center of the breast by a driver guided in a passage 320 (Fig. 4) in an abutment-post 322, this driver being fixed against movement in the corresponding 75

plunger 196. The movable sections 2 include an opposite side pair, each section inserting two nails and one rear section driving a single nail. Because there are but three movable sections, the locking members 306 are not arranged in pairs, but instead each section has a separate locking device.

In connection with the mechanism C, the holder D acts to deliver a lift supplied to it by the operator when he jacks a shoe to be heeled. This holder (Figs. 7 and 9) has a body-portion 330 provided with an outward extension 332 furnishing part of a parallel motion, the links 334 and 336 of which are pivoted to this extension and to the front of the cap-piece 197 above the opening 22 in the frame. The sides of the body-portion of the holder are flanged at 338 to furnish ways for a vertically movable slide 340 having at its lower extremity a projection 341 extending into a depression in the body-portion, in which depression is a helical spring 342 contacting with the projection and urging the slide downwardly, as appears in Fig. 7. Fulcrumed at 344 at opposite sides of the upper end of the slide are bell-crank levers 346, 346, horizontal arms of which extend toward each other and carry intermeshing gear-segments 348. Vertical arms of the levers have horizontal extensions 350 drawn normally toward each other by a connecting spring 352. The forward extremities of the extensions 350 are offset outwardly to give shoulders 354 to gage horizontally the position of a lift *h* inserted between them. The lift may be located vertically in the holding arms by recesses having upper walls overhanging the lift at 356 to receive its contact. The link 336 of the holder has formed with it an arm 358 carrying at its inner extremity a gear-segment 360 meshing with a rack-bar 362 guided for vertical movement in a slot in the cap 197 outside the turret T. At the inner side of the bar is a roll 364 lying in a cam-groove 366 formed about the turret (Fig. 3). The operator supplies a lift *h* to the holder D when he jacks a shoe and places a base upon the heel-seat, forcing said lift between the lever-extensions 350, which yield against their spring 352 to receive it. The lift is located horizontally in a predetermined position by engagement with the shoulders 354 and walls 356. Through the operations of the mechanisms A and B, the holder remains at rest, but as the turret brings the mechanism C into operating position, the cam-groove 366, acting through the gearing 360, 362, causes the holder and lift to descend, the latter entering, still in a horizontal position, between the heel-base on the jacked shoe and the lower ends of the sections 2. As the jack with the shoe S and attached base rises, the ends of the pins 34 extending above the base enter openings in the lift which are alined with them and carry up said lift and its supporting levers 346 and the slide 340, the spring 342 yielding. The lift-attaching nails having been inserted by the mechanism C and pressure released by the mechanism E, the holder D is returned by the cam-groove 366 to its normal raised position.

The distributor G, which supplies nails to all three operating mechanisms, is mounted upon standards 370 rising from the frame 20 (Figs. 2 and 14). Supported upon the standards is a table 372. At one side of and beneath this table is located a block-magazine. This magazine is shown as a vertical cabinet, normally closed at one side by a door 374 (Fig. 15), through which door may be introduced the blocks *g* loaded with

nails N. Each block is arranged as in the Pope patent previously referred to, it being provided with a retaining shutter or slide 376, upon which rest the points of the nails held in openings 378 in the block. The nails are released set by set by a step-by-step separation of the block and shutter until the nails have been delivered from the entire longitudinal series of transverse sets of openings. Above the table and magazine is a cover 380, in which are ways 382 (Fig. 16) to receive a rack-bar 384, which has a depending end-portion 386 engaging the block upon the table 372 for the purpose of bringing its sets of openings one by one into position for registration with openings 388 in a discharge-roll 390 rotatable in a casing below the table.

The stack of blocks contained in the magazine M is borne by a platform 392 mounted upon the upper end of a rack-bar 394 guided for vertical movement in the supporting structure. Upward step-by-step travel of the platform to present successive blocks at the level of the table 372 and the advance of the thus-positioned blocks from the magazine upon the table into co-operation with the bar 384 is accomplished by mechanism common to both. As illustrated in Figs. 13, 14 and 15, a spindle 400 is carried horizontally in the frame below the magazine, and upon this turns a three-armed lever 402. A horizontally extending arm 404 of the lever is joined by a link 406 to an actuating lever 408 fulcrumed at the rear of the machine (Fig. 1) and having a roll operating in a cam-groove 410 (Fig. 3) in the inner face of the gear 18. A second arm 412 of the lever 402 carries a yieldable pawl 414 engaging the teeth of the bar 394. The oscillation of the lever 402 under the influence of the cam is sufficient to cause the pawl to elevate the platform an amount equal to the thickness of one of the blocks *g*. There it is retained until the next elevating action by a spring-actuated detent 415 pivoted upon the frame. A third, vertical arm 416 of the lever 402 has co-operating with it a torsion-spring 418 surrounding the spindle 400, which spring acts to throw this arm 416 in toward the magazine and the arm 412 down in preparation for its elevating or block-presenting stroke. It is this inward movement of the arm 416 which causes the transfer of a block from the top of the stack in the magazine, to take the place upon the table 372 of a block which has been emptied of its nails. The upper end of the arm 416 has fixed in it a horizontal cross-rod 420, about the extremities of which pushing fingers 422 are free to turn. In the outer position of the arm 416, the fingers rest upon a latch-bar 424 mounted for reciprocation at the top of the outer magazine-wall. At this time, the latch-bar occupies recesses 426 in the fingers, so said fingers are held against the force of the spring 418 with their ends just outside the top block in the magazine. When the latch-bar is moved to the left (Fig. 16) in a manner to be described, recesses 428 in its upper edge are brought into alinement with the fingers, which are thereby released, so the spring 418 forces them against the outer side of the upper block. This is moved very rapidly from the magazine upon the table 372, a wall 430 of the table limiting this movement, and into co-operation with the block-feeding rack-bar 384. The releasing movement of the bar 424 is against the tension of a spring 432, which normally holds it in its latching relation. To prevent too great a shock as the blocks are stopped by the wall 430, I prefer

to cushion the movement of the arm 416. For this purpose there is fulcrumed upon the frame a bell-crank lever 434, one extremity of which has a slot receiving a pin 436 projecting from the arm 416, while the other extremity is joined by a link 438 to the piston of a dash-pot 440. While the successive sets of nails are being delivered from each block, the cam 418 is rotating idly, since it acts only in connection with the movement of the blocks in and from the magazine. Were not means taken to prevent it, an objectionable series of clicks would be produced by contact of the cam with the lever 438. The latch-bar 424 is substantially narrower than the recess 426, and has formed at the inner edge inclines 442 engaged by a corner 443 of each finger (Fig. 15). When the fingers 422 are latched to await the next block-delivery, the corners 443 of their recesses slide down the inclines, so the connections hold the lever 438 just clear of striking engagement with the cam. The angle at which the surfaces 442 lie is too steep to cause the fingers to be released by slipping upwardly, their tendency being to move down under the influence of their weight.

When a block *g* is advanced from the magazine upon the table, its shutter 376 rests in a depression, at the forward edge of which, considering the delivering movement, is a retaining shoulder 450 (Figs. 14 and 17). The block itself is wholly above this shoulder. When the feed of the block by the bar 384 occurs, the shoulder engages and holds the shutter while the block travels forward over the table. Thus the sets of openings 378 are uncovered one by one for delivery of the nails for successive heeling operations. The first set of nails should be ready for delivery by the roll 390 as soon as the block is carried into position by the fingers 422. That is, no feed of the block by the bar 384 should be necessary, since this feed occurs during a heeling operation. On the other hand, a set of the block-openings 378 cannot be advanced longitudinally of the roll 390 over openings 388, since the points of the nails would catch in the latter openings. I therefore carry the block over the table, first parallel to the axis of the roll 390 or in a direction at right angles to the movement of the bar 384, and, toward the termination of the travel, in an inclined direction having for its components movement parallel to the axis and at right angles thereto. The former introduces the shutter into the table-depression and associates the block with the bar; the latter separates the block from the shutter and produces co-operation of each block-opening with the corresponding roll-opening, without movement across associated roll-openings. Fulcrumed at the inner side of the table 372 is a bell-crank lever 452 (Fig. 16) having upon one arm a depending roll 454 lying in the path of the entering block at the end of the wall 430, while the curved extremity 456 of a second arm is situated adjacent to the end 386 of the rack-bar 384. As the block approaches the termination of its entering travel, it strikes the roll 454, swinging the lever 452 upon its fulcrum. The end 456 is thereby carried against the rack-bar, moving this and the engaged block far enough in its nail-delivering direction to align the leading row of openings in the block with the active openings of the discharge-roll 390. In its forward movement, the shutter 376 of the block is retained by the table-shoulder 450, so the first set of block-openings is freed, ready for the delivery of the corresponding

nails. At this time, the advance of the openings is at right angles to the axis of the roll, so each nail is brought directly into registration with the proper one of the set of roll-openings 388 at that time in delivering position, and is not caused to travel across other roll-openings to produce interference.

For each rotation of the turret T, the block *g* in use is to be stepped forward to present another set of nails for delivery by the roll 390 for the succeeding heel-attaching operation. Rotatable in lugs upon the cover 380 is a short shaft 460 (Figs. 14 to 17). Fixed at the inner extremity of this shaft is an arm 462, upon which is pivoted a pawl 464 engaging the rack 384. An arm 466 secured to the opposite extremity of the shaft is united by a link 468 to a lever 470 fulcrumed upon the distributor-frame. A roll at the lower extremity of this lever is held by a spring 472 against the periphery of a double-pointed cam 474 fixed upon a shaft 476 journaled transversely of the frame. Upon each complete rotation of the turret, this shaft is turned through 180°. Near the termination of each operating cycle, one of the points of the cam causes the pawl 464 to advance the block to the necessary extent. Each half-turn of the shaft 476 is in three steps corresponding to the three operating mechanisms A, B and C, it being produced by a cam-surface 478 upon the top of the turret, a lever 480 fulcrumed upon the frame and provided with a roll urged by a torsion-spring 481 into contact with the cam, a link 482, an arm 484 arranged to oscillate about the shaft 476 and one-way ratchet-connections 486. The reason for this divided actuation of the shaft is hereinafter developed.

For each advance of the block, the rack-bar 384 is retained by a detent 488 pivoted upon the cover 380 and engaging the rack. This retention is against the force, tending to return the bar to its initial position, of a weight 490 secured by a flexible member 492 to the rack-bar, the member being guided by a sheave 494. The detent is tripped after the last set of block-openings has been emptied by a projection 496 (Fig. 16) from the side of the rack-bar, this projection engaging a projection 498 depending from a slide 500 guided in the cover above the bar. Movement produced by the engagement carries the forward end of the slide against the under side of the detent 488 (Fig. 17), lifting this to free the rack-bar and holding it raised. At the termination of the return travel of the bar, a lateral projection 502 from its forward end contacts with the slide-projection 498, restoring said slide to its initial position and freeing the detent. A spring 504 mounted in the cover creates sufficient frictional resistance to movement of the slide 500 so the latter remains in place until shifted by the rack-bar. At the termination of the restoring movement of the bar, it strikes the end 458 of the lever 452 to return this to normal. In this return, a roll 506 mounted upon the end of the lever engages a lever 508 fulcrumed upon the distributor-frame. The lever 508 is thereby turned to bring a projection 510 at its outer end against the bar 424, which latches the feeding fingers 422. This shifts said bar sufficiently to bring its depressions 428 beneath the fingers, releasing these to permit them to at once feed the next block from the magazine under the influence of the spring 418. As the shutter of this succeeding block contacts with that of the previous block, it forces it from the table through a slot or elongated opening 512 at the bottom of the wall 430.

430. Each fresh block, as it is carried forward in its nail-delivering movement, contacts with the previously emptied block, and this is ejected from the apparatus, to be deposited in a receptacle.

5 It has already been explained that the delivery of nails from the distributor is in three distinct groups, containing different numbers of nails for use, respectively, at the mechanisms A, B and C. This delivery is under the control of the roll 390, 10 the openings 388 of which are arranged in three groups, each equaling in number the nails for a particular mechanism. In the present instance, these are, respectively, two, eight and six for the mechanisms A, B and C, they being successively 15 presented to the set of openings 378 in the nail-block which are at the time in position for discharge. The roll 390 is turned to aline its different groups of openings with the block-openings by spur-gearing 516 from the shaft 476. To 20 guard against misalignment of the roll-openings with the block-openings, the roll carries, fast upon it, a star-wheel 518, the depressions in the periphery of which receive a roll 529 upon the end of a retaining arm 522 pivoted upon the 25 frame and drawn into the depressions by a spring 524. The groups of openings 388 may be separated by intervals of 60°, they being brought into registration with each set of nail-block-openings 378 at one end during the rotation of 30 the roll through 180°, and with the succeeding set of block-openings at the opposite end during the remaining 180°. Since, as already described, each half-turn of the roll 390 is effected in three steps by the turret-cam 478, one of the three 35 groups of roll-openings is alined with the block-openings after the corresponding mechanism A, B or C to be supplied arrives at the operating position. From openings in the casing of the roll 390 with which the lower extremities of the 40 openings 388 are alined, flexible tubes 526 lead to openings in a foot-plate 528 suspended beneath the table 372, these openings being alined in the rotation of the turret with the openings in its extensions 195 as these come successively beneath the foot-plate. The connections of the 45 groups of tubes 526 of course correspond to the grouping of the tubes 226, so the correct number of nails is delivered to each of the mechanisms A, B and C.

50 To state in outline the manner of using this machine, the operator supplies the magazine M of the distributor G with blocks g loaded with the size of nails N proper for the heels to be attached. A block is also placed upon the table 55 372 in nail-delivering position, co-operating with the rack-bar 394. Initially, that group of the discharge-roll-openings 388 which feeds two nails is alined with the first transverse set of the block-openings 378, so these two nails at once 60 pass through the corresponding tubes 526, passages 227 and tubes 226 to the retaining members 228 in the driver-passages 222 of the post 220 of the pricking and preliminary base-attaching mechanism A. This mechanism A, at 65 the beginning of the operating cycle, is located opposite the opening 22 in the frame. For the first operation, both the jacks J and j will be out of work-receiving position, as appears in Fig. 1. To one of these, as J, the operator applies a shoe S consisting of a lasted upper with its attached insole and outsole, this shoe being held in a predetermined relation to the jack by the passage of the jack-pins 34 through previously formed openings in the heel-seat-portion of the shoe-bottom. The operator also places a

heel-base H upon the jack-pins and heel-seat, and inserts a top lift between the arms 350 of the holder D. The jack J is now pushed through the opening 22 into the machine, a portion 39 of its actuating cam 60 permitting this. When 5 the jack, in its manual travel, strikes the lever 82, the clutch 88 is engaged for actuation of the machine through a single cycle, and the automatic operation begins. First, the pressure mechanism E yieldably elevates the jack to 10 measure the heel-seat-portion of the shoe and the heel-base thereon, and then continues the upward movement positively to clamp the work against the ends of the post 229 and of the sections x of the mechanism A. In the establishment 15 of engagement between the work and the sections, the latter yield against their springs 248, so they are located with their awl-passages 249 and 242 at definite distances from the periphery of the base. The plunger 196 of the mechanism A is engaged by the connecting member 280 of the actuating mechanism F, which now begins its 20 downward movement. This first locks the sections x by the wedging actions of the rod-portions 300, and causes the insertion of the two 25 preliminary base-attaching nails at a, and the pricking in the base by the awls 260 of eight nail-receiving openings p. After this, the plunger is elevated by the actuating mechanism F, the sections x are unlocked for return by their springs 30 to their normal inner positions, and the jack is lowered by the pressure mechanism E. The turret T now rotates through 120°, bringing the base-nailing mechanism B into operating position over the jacked work, and with its plunger 35 196 in engagement with the connecting member 280 of the actuating mechanism F. The discharge-roll 390 of the nail-distributor G thereupon rotates through 60°, bringing its group of eight openings into registration with the tubes 40 526 to make a delivery of the base-attaching nails to the sections y. In connection with this mechanism B, the application of pressure to the work, the locking of the sections and the insertion of the nails are effected in the same manner 45 as just described for mechanism A, save here the driving of all the nails is performed by the yieldable sections, the nails being inserted at b in the pricked openings p. Also, for mechanism C, which is brought into co-operation with the 50 work by a further 120° rotation of the turret, the insertion of the six lift-attaching nails at c takes place through a series of actions similar to those for mechanism B, these nails having been fed to the sections z upon 60° of additional rotation 55 of the discharge-roll 390. It is to be noted, in this connection, that when the turret brings the mechanism C to rest opposite the opening 22, the lift-holder D is automatically carried in to interpose a lift h between the already nailed 60 base H and the pressure-receiving surfaces of the mechanism C, so this lift is carried up against said surfaces when the jack J is raised by the pressure mechanism E. Further, if a rubber lift is to be attached, the actuating mechanism of 65 the wedge 170 is so set that the clamping pressure of the mechanism E is automatically reduced, preventing the yieldable lift from being unduly compressed. During the automatic heel-70 ing operation, which has just been described in connection with the jack J, the operator has been preparing another shoe for heeling upon the jack j, and when the machine throws out the former jack with the finished work, he swings in the jack j for the succeeding operation. After 75

the delivery of the last group of six nails by the discharge-roll 390 for the first heel-attaching operation, this roll turns through 60° to bring the first group of two openings into nail-delivering position, and the actuating mechanism of the feeding pawl 464 advances the block *g* one step to bring a second set of nail-openings 318 into delivering relation to the roll. This continues until all the sets of openings in the longitudinal series have been used. The rack-bar 384, which has been advancing the block, is thereupon released from its retaining detent 488 and returned to its initial position by the weight 490. At the completion of this reverse movement, the rack-bar shifts the lever 508 and thus the latch-bar 424 to release the fingers 422, spring-actuated under the influence of the lever 416. The fingers, thus freed, carry forward a full block *g* from the top of the stack in the magazine M into nail-delivering position upon the table 372 in co-operation with the rack-bar, this occurring only when the bar is in position to receive the block. The stack in the magazine is elevated to present another block at the transferring level, this being effected by the lever 416 when said lever is moved out under the power of the machine to be latched by the bar 424. It will be seen that the supply of nails to the operating mechanisms A, B and C is made entirely automatic for all the sets of openings of all the blocks *g* contained in the magazine.

Having described my invention, what I claim as new and desire to secure by Letters Patent of the United States is:

- 35 1. In a shoe machine, a plurality of operating mechanisms movable to an operating position common to all, a plurality of work-supports movable to receive the action of the mechanisms at said common operating position, and means for moving the supports and mechanism to and from the common operating position in definite time-relation to each other, the work being retained by each support at such position to receive the successive action of the operating mechanisms.
- 40 2. In a heel-attaching machine, plural mechanisms for operating upon heels; said mechanisms being movable to a position common to all and there movable to perform an operation upon a heel, a plurality of jacks movable to receive the action of the mechanisms at said common operating position, and means for moving the jacks successively to the operating position and for moving all the operating mechanisms into co-operation with each jack.
- 45 3. In a shoe machine, a plurality of operating mechanisms movable into operating position, a plurality of work-supports arranged for movement independently of each other into and out of operating position, and means for moving the mechanisms and supports to the operating position.
- 50 4. In a heel-attaching machine, plural mechanisms for operating upon heels, said mechanisms being movable to an operating position common to all, a plurality of jacks movable to receive the action of the mechanisms at said common operating position, means made effective by the machine for moving the jacks successively to the operating position, said jacks being movable by the operator independently of each other, and means actuated by the machine for moving all the operating mechanisms into co-operation with each jack.
- 55 5. In a shoe machine, a rotatable turret, a plurality of operating mechanisms mounted upon the turret, means for rotating the turret to successively present the mechanisms at an operating position, oscillatory work-supports, and means for moving the work-supports into registration with the operating mechanisms at the operating position.

6. In a heel-attaching machine, a rotatable turret, a plurality of nailing mechanisms mounted upon the turret, means for rotating the turret to successively present the nailing mechanisms at an operating position, a plurality of movable jacks, and means for successively moving the jacks to the operating position into registration with the successively presented nailing mechanisms.

7. In a heel-attaching machine, a rotatable turret, pricking mechanism, base-nailing mechanism and lift-nailing mechanism mounted upon the turret, means for rotating the turret to successively present the mechanisms at an operating position, two jacks, and means for moving the jacks alternately to the operating position to register with the successively presented mechanisms.

8. In a shoe machine, a plurality of operating mechanisms movable to an operating position common to all, an actuating member at said position into engagement with which the operating mechanisms move, and a plurality of movable supports arranged to successively present shoes to receive the action of all the operating mechanisms under the influence of the actuating member.

9. In a shoe machine, a plurality of operating mechanisms movable to an operating position common to all, an actuating member at said position into engagement with which the operating mechanisms move, a plurality of movable supports arranged to successively present shoes to receive the action of all the operating mechanisms under the influence of the actuating member, and means for moving the mechanisms, member and supports in definite time-relation.

10. In a heel-attaching machine, plural mechanisms for operating upon heels, said mechanisms being movable to an operating position common to all, an actuating member at said operating position and into successive engagement with which the operating mechanisms are moved, and a plurality of jacks movable to the common operating position to receive the action of all the operating mechanisms.

11. In a shoe machine, a plurality of operating mechanisms movable to an operating position common to all, a plurality of work-supports movable to receive the action of the mechanisms at said common operating position, mechanism common to plural work-supports at the operating position and arranged to move them toward the operating mechanisms to apply pressure to the work, and means for moving the supports and mechanisms in definite time-relation.

12. In a heel-attaching machine, plural mechanisms for operating upon heels, said mechanisms being movable to an operating position common to all, a plurality of jacks movable to receive the action of the mechanisms at said common operating position, pressure mechanism at the operating position into co-operation with which the jacks move and which move said jacks toward the operating mechanisms, and means for moving the jacks successively to the operating position and for moving all the operating mechanisms into co-operation with each jack.

13. In a shoe machine, a plurality of operating mechanisms movable to an operating position common to all, an actuating member at said position into engagement with which the operating mechanisms move, plural supports arranged to present work at the operating position to the operating mechanisms when they are actuated by the member, and pressure mechanism common to plural work-supports for moving said work-supports at the operating position. 5
14. In a shoe machine, a plurality of operating mechanisms movable to an operating position common to all, an actuating member at said position into engagement with which the operating mechanisms move, a plurality of movable supports arranged to successively present shoes to receive the action of all the operating mechanisms under the influence of the actuating member, pressure mechanism for moving the work-supports at the operating position and into cooperation with which said work-supports move, and means for moving the mechanisms, member and supports in definite time-relation. 10
15. In a heel-attaching machine, plural mechanisms for operating upon heels, said mechanisms being movable to an operating position common to all, an actuating member at said operating position for the operating mechanisms, a plurality of jacks movable to the common operating position to receive the action of all the operating mechanisms, and pressure mechanism at the operating position arranged to move the jacks and into engagement with which said jacks move. 15
16. In a shoe machine, a plurality of nailing mechanisms, means for operating the plural mechanisms at different times, a unitary holder constructed and arranged to hold nails separate from one another, and means arranged to deliver nails from the holder to plural nailing mechanisms. 20
17. In a shoe machine, a plurality of nailing mechanisms, a unitary holder constructed and arranged to hold nails separate from one another, and means arranged to deliver different numbers of nails from the holder to different nailing mechanisms. 25
18. In a shoe machine, a plurality of nailing mechanisms arranged to operate successively on each shoe, a unitary holder arranged to hold nails in a series of sets, means arranged to deliver nails from one set to different nailing mechanisms for a piece of work, and means for similarly delivering nails from another of the sets for another piece of work. 30
19. In a shoe machine, a plurality of nailing mechanisms, means for operating the plural mechanisms successively, a block provided with nail-holding openings, and means arranged to deliver nails from certain of the openings to one nailing mechanism and nails from other openings to another nailing mechanism. 35
20. In a shoe machine, a plurality of nailing mechanisms, a block provided with nail-holding openings arranged in sets, there being a series of said sets, a device delivering nails in certain of the openings of a set to one nailing mechanism and nails in a different number of other openings of said set to another nailing mechanism, and means for advancing the block to present another set of openings of the series to the delivering device. 40
21. In a heel-attaching machine, heel-pricking mechanism provided with means arranged to insert a heel-attaching nail simultaneously with the pricking operation, mechanism arranged to insert nails in the pricked openings, and a nail-holder arranged to deliver nails to the pricking mechanism and to the nail-inserting mechanism. 45
22. In a heel-attaching machine, heel-pricking mechanism provided with means arranged to insert a heel-attaching nail, mechanism arranged to insert nails in the pricked openings, a block provided with nail-holding openings, and means arranged to deliver nails from certain of the openings to the pricking mechanism and from other openings to the inserting mechanism. 50
23. In a heel-attaching machine, base-nailing mechanism, lift-nailing mechanism, a block provided with nail-holding openings, and means arranged to deliver nails from certain of the openings to the base-nailing mechanism and from other openings to the lift-nailing mechanism. 55
24. In a heel-attaching machine, base-pricking and nail-driving mechanism, base-nailing mechanism, lift-nailing mechanism, a block provided with nail-holding openings, and means arranged to deliver nails from certain of the openings to each of the base-nailing mechanisms and from other openings to the lift-nailing mechanism. 60
25. In a shoe machine, a plurality of work-supports movable into and out of operating position, a plurality of nailing mechanisms for operating upon the work on each support at said operating position, a nail-holder, and nail-delivering connections between the holder and plural nailing mechanisms. 65
26. In a shoe machine, a plurality of work-supports movable into and out of operating position, a plurality of nailing mechanisms for operating upon the work on each support at said operating position, a nail-holder, nail-delivering connections between the holder and plural nailing mechanisms, and means arranged to deliver through the connections different numbers of nails to different mechanisms. 70
27. In a shoe machine, a plurality of work-supports movable into and out of operating position, a plurality of nailing mechanisms for operating upon the work on each support at said operating position, a movable holder provided with nail-receiving openings arranged in a series of sets, and connections from different openings in each set for different nailing mechanisms. 75
28. In a shoe machine, a plurality of work-supports movable into and out of operating position, a plurality of nailing mechanisms for operating upon the work on each support at said operating position, a movable holder provided with nail-receiving openings arranged in a series of sets, connections from different openings in each set for different nailing mechanisms, and means for moving the holder to present different sets of openings to the connections for insertion of the delivered nails in work upon different supports. 80
29. In a heel-attaching machine, two jacks movable alternately into and out of operating position, a rotatable turret, a plurality of nailing mechanisms successively presented by the turret at the operating position, a nail-holder, and nail-delivering connections from the holder to which the nailing mechanisms are successively presented. 85
30. In a heel-attaching machine, two jacks movable alternately into and out of operating position, a rotatable turret, a plurality of nailing mechanisms successively presented by the turret at the operating position, a block provided with nail-holding openings, nail-delivering 90

connections between the block and nailing mechanisms, and means for delivering nails in different groups from the block to different nailing mechanisms.

5 31. In a heel-attaching machine, two jacks movable alternately into and out of operating position, a rotatable turret, a plurality of nailing mechanisms successively presented by the turret at the operating position, a movable block provided with a series of sets of nail-holding openings, nail-delivering connections between the block and nailing mechanisms, and means for moving the block to present different sets of openings to the connections for insertion in work upon different jacks.

10 32. In a heel-attaching machine, two jacks movable alternately into and out of operating position, a rotatable turret, a plurality of nailing mechanisms successively presented by the turret at the operating position, a movable block provided with a series of sets of nail-holding openings, nail-delivering connections between the block and nailing mechanisms, means for delivering from each set of openings to the connections 20 25 nails in different groups, and means for moving the block to present different sets of openings to the connections for insertion in work upon different jacks.

30 33. In a heel-attaching machine, a frame, operating mechanism mounted thereon, an arm pivoted upon the frame about a vertical axis at each side of the operating mechanism, the vertical axis of the operating mechanism and the axes of the arms bearing a fixed relation to one another, and 35 a jack carried by each arm and movable into co-operation with the operating mechanism.

40 34. In a heel-attaching machine, a frame, operating mechanism mounted thereon, an arm pivoted upon the frame at each side of the operating mechanism, and a jack movable upon each arm and movable thereby into co-operation with the operating mechanism.

45 35. In a heel-attaching machine, a frame, operating mechanism mounted thereon, an arm pivoted upon the frame at each side of the operating mechanism, a jack movable upon each arm and movable thereby into co-operation with the operating mechanism, and work-locating pins rising from the jacks.

50 36. In a heel-attaching machine, a frame provided with an opening, operating mechanism mounted within the frame opposite the opening, and a jack carried by the frame at each side of the opening, each jack being movable horizontally toward the companion jack and then through said opening into co-operation with the operating mechanism.

55 37. In a heel-attaching machine, a frame provided with an opening, operating mechanism mounted within the frame opposite the opening and otherwise enclosed by said frame, an arm pivoted upon the frame beside the opening, and a jack carried by the arm and movable thereby through the opening into the enclosure for co-operation with the operating mechanism.

60 38. In a heel-attaching machine, a frame provided at its front with an opening, a turret rotatable within the frame, operating mechanisms presented successively by the turret opposite the opening, and a jack carried by the frame at the front and at each side of the opening, each jack being movable therethrough in alternation with the companion jack into co-operation with the operating mechanisms.

70 75 39. In a machine for operating upon shoes,

operating mechanism, a work-support movable in opposite directions into and out of co-operation with the operating mechanism, and means arranged to position the support in substantially the same angular relation at its extremes of 5 movement.

40. In a machine for operating upon shoes, operating mechanism, a work-support movable into and out of co-operation with the operating mechanism, and means arranged to maintain the 10 support in substantially the same angular relation to the associated elements throughout its movement.

41. In a heel-attaching machine, a frame, operating mechanism mounted thereon, an arm 15 pivoted upon the frame at each side of the operating mechanism, a jack carried by each arm and movable into co-operation with the operating mechanism, and means for turning the jacks upon the arms during the movement of said arms. 20

42. In a heel-attaching machine, a frame, nailing mechanism mounted thereon, an arm pivoted upon the frame adjacent to the nailing mechanism, a jack movable upon the arm, and 25 connections between the jack and frame arranged to move the jack upon the arm during the movement of said arm.

43. In a heel-attaching machine, a frame, nailing mechanism mounted thereon, a hollow arm pivoted upon the frame adjacent to the nailing 30 mechanism, a jack movable upon the arm, and connections to the jack extending through the arm and arranged to move the jack upon said arm.

44. In a shoe machine, operating mechanism, 35 a work-support movable between a work-receiving position and a position in registration with the operating mechanism, and a member imparting such movement to the support in opposite directions, such member leaving a portion of the movement free for performance by the operator in the 40 same direction as that imparted by the moving means.

45. In a shoe machine, operating mechanism, a work-support initially movable by the operator 45 between a work-receiving position and a position in registration with the operating mechanism, and a member for continuing the movement of the support in the same direction as that imparted by the operator to the operating position, 50 holding the support in place during the operation and thereafter moving it from the operating position.

46. In a shoe machine, operating mechanism, a work-support initially movable by the operator 55 from a work-receiving position toward the operating mechanism, and a member for continuing the movement of the support in the same direction as that imparted by the operator to the operating position, holding the support in place during the operation and thereafter moving it 60 from the operating position, the member during the last-mentioned movement leaving the support free for actuation by the operator.

47. In a shoe machine, operating mechanism, 65 two work-supporting jacks alternately movable into and out of operating position, means acting under the power of the machine and common to both supports for effecting such movement, and means under the control of an operator for separately initiating the action of the power means upon each jack.

48. In a heel-attaching machine, nailing mechanism, a jack movable forward and back at one side of the nailing mechanism, a jack similarly 75

movable at the opposite side of said mechanism, the jack-movements being between an idle position and an operating position, a heel-holder into cooperation with which the jacks move, an actuating member movable under the power of the machine, and actuating connections from said member to both jacks for causing their reverse movement.

49. In a heel-attaching machine, nailing mechanism, an arm pivoted at each side of the nailing mechanism, a jack carried by each arm and arranged to present a jacked shoe to the nailing mechanism, a rotatable cam, and connections to each arm acted upon by the cam.

50. In a heel-attaching machine, nailing mechanism, an arm pivoted at each side of the nailing mechanism, a jack carried by each arm, a rotatable member provided with a cam-groove, said groove having a portion substantially parallel to the axis of rotation, and connections to both arms, the connections from each arm having a portion entering the groove.

51. In a shoe machine, operating mechanism, a work-support, means for moving the support into and out of operating position, and a member arranged to determine the position of the support against movement in either direction at both extremes of travel.

52. In a shoe machine, operating mechanism, a work-support, means for moving the support into and out of operating position, a member movable with the support and provided with locating means corresponding to extreme positions of the support, and a member arranged to engage said locating means.

53. In a heel-attaching machine, nailing mechanism, a pivoted arm, a jack carried by the arm for movement between work-receiving position and a position for co-operation with the nailing mechanism, a member turning with the arm and provided with depressions corresponding to the work-receiving position and to the operating position of the jack, and retaining means arranged to enter the depressions.

54. In a heel-attaching machine, nailing mechanism, a pivoted arm, a jack carried by the arm for movement between work-receiving position and a position of co-operation with the nailing mechanism, a sector-plate associated with the arm and provided with depressions at its arcuate edge, and a yieldable retaining member contacting with said edge.

55. In a shoe machine, operating mechanism, a work-support movable toward and from the operating mechanism, means for imparting movement to the support, such moving means leaving a portion of the movement free for performance by the operator, driving mechanism for the machine, and controlling means for the driving mechanism actuated by the work-support during movement by the operator.

56. In a shoe machine, operating mechanism, two work-supports alternately movable into and out of operating position, means common to both supports for effecting such movement, driving mechanism for the machine, and controlling mechanism for the driving mechanism arranged for actuation in the movement of both work-supports.

57. In a heel-attaching machine, nailing mechanism, a jack movable adjacent to the nailing mechanism, a movable actuating member, connections through which movement of the member actuates the jack, driving mechanism for the actuating member, and controlling connections

for the driving mechanism arranged for actuation in the movement of the jack.

58. In a heel-attaching machine, nailing mechanism, a jack movable at each side of the nailing mechanism, a movable actuating member, connections through which movement of said member actuates both jacks, driving mechanism for the actuating member, and controlling connections for the driving mechanism arranged for actuation in the movement of both jacks.

59. In a heel-attaching machine, nail-driving mechanism, a movable jack, mechanism for moving the jack and also the driving mechanism to insert nails in the jacked work, such moving mechanism including a clutch, and means acting upon contact between an element movable with the jack and an element at the nailing mechanism for causing the engagement of the clutch.

60. In a heel-attaching machine, nailing mechanism, having reciprocatory drivers, a jack movable into and out of co-operation with the nailing mechanism, mechanism for moving the jack and reciprocating the nail-drivers, and means acting upon the arrival of the jack in co-operation with the nailing mechanism and before engagement between the jacked work and said nailing mechanism for starting the moving mechanism in operation.

61. In a heel-attaching machine, nailing mechanism, an arm pivoted adjacent thereto, a jack mounted upon the arm and movable into and out of co-operation with the nailing mechanism, mechanism for moving the arm about its pivot and including a clutch, a lever fulcrumed adjacent to the nailing mechanism and engaged by the arm as it approaches the nailing position, and connections between the lever and clutch.

62. In a shoe machine, operating mechanism, a plurality of work-supports separately movable into operating position, and a plurality of pressure mechanisms acting upon the arrival of each work-support at operating position and before its withdrawal therefrom to successively create pressure upon the work in preparation for the action of the operating mechanism.

63. In a shoe machine, operating mechanism, a plurality of work-supports separately movable to an operating position common to such supports, and a plurality of pressure mechanisms acting upon each support in the common operating position.

64. In a shoe machine, a group of operating means movable to an operating position, a group of work-supporting means movable to the same operating position, a member located at said operating position and into engagement with which the means of one of the groups successively moves, means for moving the member to create pressure upon the work, and means for further moving the member to increase the pressure.

65. In a heel-attaching machine, nailing mechanism at an operating position, a plurality of jacks movable into co-operation with the nailing mechanism at said operating position, a member at the operating position into engagement with which the jacks move, mechanism for moving the member to apply measuring pressure to the jacked work, and mechanism for moving the member to apply clamping pressure to said work.

66. In a heel-attaching machine, nailing mechanism, a plurality of jacks movable into co-operation with the nailing mechanism, a slide into engagement with which the jacks are movable, a screw threaded into the slide, and means for rotating the screw.

67. In a heel-attaching machine, nailing mechanism, a jack movable into co-operation with the nailing mechanism, a slide into engagement with which the jack is movable, a screw threaded into the slide, and means for rotating the screw, such 5 rotating means including a frictional connection.

68. In a heel-attaching machine, nailing mechanism, a jack movable into co-operation with the nailing mechanism, a slide into engagement with 10 which the jack is movable, a screw threaded into the slide, a slide carrying the screw, means for rotating the screw, and means for moving the screw-carrying slide.

69. In a heel-attaching machine, nailing mechanism, a jack movable into co-operation with the nailing mechanism, a slide into engagement with which the jack is movable, a screw threaded into the slide, a slide carrying the screw, means for 15 rotating the screw, and a cam upon which the screw-carrying slide is supported.

70. In a shoe machine, operating mechanism, a plurality of work-supports separately movable into operating position, pressure means arranged to act upon each piece of supported work a 25 plurality of times, and means made effective in each cycle of the machine for varying the applied pressure.

71. In a shoe machine, a work-support, a plurality of operating mechanisms, means for 30 moving the support and operating mechanisms relatively to bring the work and mechanisms into operating relation, pressure mechanism arranged for co-operation with plural operating mechanisms, and means for varying the pressure 35 produced upon the work for different operating mechanisms.

72. In a shoe machine, a work-support, a plurality of operating mechanisms, means for moving the operating mechanisms into successive 40 co-operation with the support, pressure mechanism successively acting upon the support for different operating mechanisms, and means for varying for different operations of the pressure mechanism the pressure created upon the work.

73. In a shoe machine, a plurality of work-supports successively movable into operating position, a plurality of mechanisms movable into position to operate upon the work on each support, pressure mechanism into co-operation with 45 which the work-supports are carried, and means for varying the pressure imparted by the mechanism to the work during the action of different operating mechanisms.

74. In a heel-attaching machine, a jack, base-nailing mechanism for co-operation with the jack, lift-nailing mechanism for co-operation with the jack, mechanism arranged to create pressure between the jacked work and the nailing mechanisms, and means for creating different pressures upon the work between the base-nailing mechanism and lift-nailing mechanism, 50 respectively, and the jack.

75. In a heel-attaching machine, a jack, base-nailing mechanism for co-operation with the jack, lift-nailing mechanism for co-operation with the jack, mechanism arranged to create pressure between the jacked work and the nailing mechanisms, and means for decreasing the pressure applied upon co-operation of the jack and lift-nailing mechanism over that applied 55 upon co-operation of the jack and base-nailing mechanism.

76. In a heel-attaching machine, a jack, a rotatable turret, nailing mechanisms mounted 70 upon the turret and movable thereby into co-

operation with the jack, pressure mechanism for moving the jack into co-operation with different nailing mechanisms, and means for producing a different extent of travel of the jack for different nailing mechanisms.

77. In a heel-attaching machine, a jack, a rotatable turret, base-nailing mechanism and lift-nailing mechanism mounted upon the turret and movable thereby into successive co-operation with the jack, pressure mechanism for moving the jack in co-operation with the nailing mechanism, and means for producing a shorter travel of the jack in co-operation with the lift-nailing mechanism than in co-operation with the base-nailing mechanism.

78. In a heel-attaching machine, two jacks arranged for alternate movement into operating position, a rotatable turret, nailing mechanisms mounted upon the turret and movable thereby into co-operation with the jack, pressure mechanism into engagement with which the jacks move, and means for varying the effect of the pressure mechanism upon each jack during its co-operation with different nailing mechanisms.

79. In a shoe machine, operating mechanism, a work-support co-operating therewith, means for moving the operating mechanism and work-support relatively to create pressure upon the work, a normally stationary abutment with which the moving means contacts, and means for adjusting the position of the abutment during each 30 operating cycle of the machine.

80. In a shoe machine, operating mechanism, a work-support co-operating therewith, a member for moving the operating mechanism and support relatively to create pressure upon the work, a slide upon which the member is mounted, a normally stationary abutment with which the member contacts, and means for moving the abutment toward and from the slide.

81. In a shoe machine, operating mechanism, a work-support co-operating therewith, a slide connected to the work-support, a lever fulcrumed upon the slide, and an abutment with which the lever contacts.

82. In a shoe machine, operating mechanism, a work-support co-operating therewith, a slide connected to the work-support, a lever fulcrumed upon the slide, an abutment with which the lever contacts, and means for altering the position 50 of the abutment.

83. In a shoe machine, operating mechanism, a work-support co-operating therewith, a slide connected to the work-support, a lever fulcrumed upon the slide, a movable abutment with which the lever contacts, a wedge contacting with the abutment, and means for reciprocating the wedge.

84. In a heel-attaching machine, a rotatable turret having spaced plates, groups of nail-inserting sections movable upon one plate, and springs carried by another plate for actuating the sections.

85. In a heel-attaching machine, a rotatable turret having upper and lower plates, groups of nail-inserting sections movable upon the upper plate, a post associated with each group of sections and depending from the upper plate for contact with the work, and springs carried by the lower plate for actuating the sections.

86. In a heel-attaching machine, a rotatable turret having spaced plates, groups of nail-inserting sections movable upon one plate, and locking devices for the sections carried by another plate.

87. In a heel-attaching machine, a rotatable turret having upper and lower plates, groups of nail-inserting sections movable upon the upper plate, springs carried by the lower plate for actuating the sections, and locking devices for the sections movable upon the lower plate. 5
88. In a heel-attaching machine, a rotatable turret, work-engaging posts depending from the turret and spaced from one another, and a group of nail-inserting sections pivoted upon the turret about each of the posts for movement toward and from the respective posts. 10
89. In a heel-attaching machine, a rotatable turret having a plate provided with a plurality of tubular upward extensions, plungers movable in the extensions, nail-inserting sections pivoted upon the plate in groups corresponding to the extensions, nail-drivers operating in the sections, and connections between each plunger and the drivers of its nail-inserting sections. 15
90. In a heel-attaching machine, a rotatable turret having upper and lower plates, the upper plate being provided with a plurality of tubular upward extensions, plungers movable in the turret-extensions, nail-inserting sections pivoted at the under side of the upper plate in groups corresponding to the extensions, nail-drivers operating in the sections, locking devices for the sections carried by the lower plate, and connections between each plunger and the drivers and locking devices of its nail-inserting sections. 20
91. In a heel-attaching machine, a frame, a turret rotatable in the frame about a vertical axis, nail-inserting mechanisms carried by the turret, a jack into co-operation with which the nail-inserting mechanisms are carried by the turret, means for successively creating pressure upon the work between the nail-inserting mechanisms and jack, and a cap-piece secured to the frame and overhanging the turret for contact therewith upon the application of pressure to the work. 25
92. In a machine for operating upon the heel-portions of shoes, a shoe-support, pricking mechanism co-operating with the support and including nail-driving means, and means for moving the pricking and driving instrumentalities simultaneously toward the support to produce their action. 30
93. In a machine for operating upon the heel-portions of shoes, a shoe-support, an abutment member co-operating with the support and having a nail-receiving passage, a driver movable in the passage, pricking sections associated with the abutment and provided with passages, and awls movable in the passages. 35
94. In a machine for operating upon the heel-portions of shoes, a shoe-support, an abutment-post co-operating with the support and having a nail-receiving passage, a driver movable in the passage, pricking sections co-operating with and movable relatively to the post and provided with passages, and awls movable in the passages. 40
95. In a machine for operating upon the heel-portions of shoes, a jack, a turret rotatable in proximity to the jack, pricking mechanism movable by the turret into co-operation with the jack and including nail-driving means, and means for operating the mechanism to effect simultaneously the pricking and nail-driving. 45
96. In a machine for operating upon the heel-portions of shoes, a jack, a turret rotatable in proximity to the jack, a post fixed upon the turret and movable thereby into co-operation with the jack, said post having a nail-receiving 50
- passage, a driver movable in the passage, pricking sections pivoted on the turret about the post and each provided with a passage, and awls movable in the passages. 55
97. In a nail-driving machine, a nail-inserting section having a driver-passage and a nail-delivering passage, a driver operating in the driver-passage, and a nail-stop pivoted at the juncture of the passages and having a wall normally in substantial alinement with a wall of the nail-delivering passage and a second wall movable across said nail-delivering passage. 60
98. In a nail-driving machine, a nail-inserting section having a driver-passage and a nail-delivering passage, a driver operating in the driver-passage, and a nail-stop pivoted at the juncture of the passages and having a wall normally in substantial alinement with a wall of the nail-delivering passage and an arcuate wall intersecting the first-mentioned wall and movable across said nail-delivering passage. 65
99. In a nail-driving machine, a nail-inserting section having a driver-passage and a nail-delivering passage, a driver operating in the driver-passage, a recess in the section opening into the driver-passage at one side, and a nail-stop arranged to oscillate in the recess and having two intersecting nail-retaining peripheral portions. 70
100. In a nail-driving machine, a nail-inserting section having a driver-passage and a nail-delivering passage, a driver operating in the driver-passage, a recess in the section opening into the driver-passage at one side, a nail-stop arranged to oscillate in the recess and having two intersecting nail-retaining peripheral portions, and a spring seated in the recess and acting upon the stop to hold the driver-passage normally closed. 75
101. In a shoe machine, a work-support, a plurality of pricking sections movable toward and from the support, awls operating in the sections, means for moving the plural sections together into and out of cooperation with the support, and springs forcing the individual sections normally toward the support. 80
102. In a shoe machine, a work-support, pricking sections movable toward and from the support, a plurality of the sections being each provided with a plurality of awl-passages, and awls operating in the passages. 85
103. In a shoe machine, a work-support, pricking sections movable toward and from the support, a plurality of the sections being each provided with a plurality of awl-passages, awls operating in the passages, means for reciprocating the awls in the passages, and means for forcing the sections toward the support. 90
104. In a shoe machine, a work-support, a plurality of pricking sections movable toward and from the support, awls operating in the sections, plungers guided adjacent to the sections at the sides opposite the support, and springs arranged to force the plungers against the sections. 95
105. In a heel-attaching machine, a rotatable turret comprising spaced plates, operating sections movable upon one of the plates, and springs carried by a second plate and acting upon the sections. 100
106. In a heel-attaching machine, a rotatable turret comprising upper and lower plates, sections pivoted upon the upper plate and provided with awl-passages, awls movable in the passages, and springs carried by the lower plate and acting upon the sections. 105

107. In a shoe machine, a work-support, a plurality of pricking sections movable toward and from the support and having gage-portions arranged for contact with the supported work, awls 5 operating in the sections, means for moving the plural sections together into and out of co-operation with the support, and means for forcing the individual sections toward the support with the gage-portions in contact with the work.
108. In a shoe machine, a work-support, a plurality of pricking sections movable toward and from the support and each having a gage-portion provided with an edge arranged for contact with the supported work and including an upwardly and inwardly inclined surface, awls operating in the sections, and means for forcing the sections toward the support with the gage-portions in contact with the work.
109. In a heel-attaching machine, a jack, a plurality of pricking sections pivotally mounted about said jack and each having a gage-portion arranged for contact with a heel carried by a jacked shoe, awls operating in the sections, means for forcing the sections toward the jack, and means 25 for moving all the sections, together to cause the gage-portions to contact with the edge of the heel.
110. In a heel-attaching machine, a jack, a plurality of pricking sections pivotally mounted about 30 said jack and each having a gage-portion provided with an inwardly and upwardly inclined edge arranged for contact with a heel carried by a jacked shoe, awls operating in the sections, and springs forcing the sections toward the jack.
111. In a shoe machine, a rotatable turret, operating sections movable upon the turret and each having a passage, tools arranged to reciprocate in the passages, a plunger movable in the turret, and actuating connections between the plunger 35 and tools.
112. In a shoe machine, a rotatable turret having a tubular extension, operating sections movable upon the turret and each having a passage, tools arranged to reciprocate in the passages, a plunger reciprocating in the turret-extension, and links pivoted to the plunger and tools.
113. In a heel-attaching machine, a rotatable turret, pricking sections carried by the turret and each having a passage, awls arranged to reciprocate in the passages, a plunger movable in the 50 turret, and connections between the plunger and awls.
114. In a shoe machine, a rotatable turret, operating sections mounted upon the turret and each having a passage, a tool movable in each passage, a reciprocatory member movable in the turret and connected to the tools, and an actuating member into engagement with which the reciprocatory member is carried by the turret in 55 its rotation.
115. In a shoe machine, a rotatable turret, pricking sections mounted upon the turret and each having a passage, an awl movable in each passage, a reciprocatory member movable upon the turret and connected to the awls, and an actuating member mounted for movement independently of the turret and engaging the reciprocatory member.
116. In a shoe machine, a rotatable turret, nailing sections mounted upon the turret and each having a passage, a nail-driver movable in each passage, a reciprocatory member mounted upon the turret and connected to the drivers, and an actuating member mounted for movement inde- 70 pendently of the turret and engaging the reciprocatory member.
117. In a shoe machine, a rotatable turret, a group of pricking sections mounted upon the turret and each having a passage, an awl movable 5 in each passage, a group of nailing sections mounted upon the turret, each nailing section having a passage, a nail-driver movable in each passage of the nailing sections, a plunger for each group of sections mounted upon the turret, and an actuating member into co-operation with which the plunger is moved by the turret.
118. In a shoe machine, a rotatable turret, a plurality of groups of nailing sections mounted upon the turret and each section having a passage, a nail-driver movable in each passage, a plunger for each group of sections mounted upon the turret, and an actuating member into co-operation with which the plungers are moved by the turret.
119. In a heel-attaching machine, a frame, a turret rotatable thereon, a group of operating sections pivoted upon the turret and each having a passage, a tool movable in each passage, a plunger mounted upon the turret and connected 25 to the tools, a lever fulcrumed upon the frame, and means for connecting the plunger and lever as the turret rotates.
120. In a heel-attaching machine, a frame, a turret rotatable thereon, a group of operating 30 sections pivoted upon the turret and each having a passage, a tool movable in each passage, a plunger mounted upon the turret and connected to the tools, a lever fulcrumed upon the frame, and a connecting member pivoted upon the 35 frame, the plunger and connecting member being provided with co-operating ways and projections.
121. In a shoe machine, a rotatable turret, operating sections mounted upon the turret and each having a passage, a tool movable in each 40 passage, a reciprocatory member movable in a turret and connected to the tools, an actuating member into engagement with which the reciprocatory member is carried by the turret in its rotation, and connections for moving the 45 member extending axially of the turret.
122. In a heel-attaching machine, a frame, a turret rotatable thereon, a group of operating sections pivoted upon the turret and each having a passage, a tool movable in each passage, a plunger mounted upon the turret and connected 50 to the tools, a lever fulcrumed upon the frame, means for connecting the plunger and lever as the turret rotates, and a connecting-rod pivoted to the lever and extending axially of the turret.
123. In a shoe machine, a rotatable turret, operating sections mounted upon the turret and each having a passage, a tool movable in each passage, a reciprocatory member movable in the 55 turret and connected to the tools, an actuating member into engagement with which the reciprocatory member is carried by the turret in its rotation, and means arranged to retain the reciprocatory member in position to receive the engagement of the actuating member when said plunger and actuating member are disengaged.
124. In a shoe machine, a rotatable turret, operating sections mounted upon the turret and each having a passage, a tool movable in each 70 passage, a reciprocatory member movable in the turret and connected to the tools, an actuating member into engagement with which the reciprocatory member is carried by the turret in its rotation, and a latch connecting the turret and reciprocatory member.

125. In a heel-attaching machine, a frame, a turret rotatable thereon, a group of operating sections pivoted upon the turret and each having a passage, a tool movable in each passage, a plunger mounted upon the turret and connected to the tools, a yieldable latch movable upon the turret and engaging the plunger, a lever fulcrumed upon the frame, and means for connecting the plunger and lever as the turret rotates. 5
126. In a shoe machine, a movable turret, operating sections mounted upon the turret and each having a passage, a tool movable in each passage, a reciprocatory member movable in the turret and connected to the tools, a chain of actuating elements connected to the reciprocatory member and capable of movement independently of one another, and means arranged to retain the elements in a definite normal relation. 10
127. In a shoe machine, a rotatable turret, operating sections mounted upon the turret and each having a passage, a tool movable in each passage, a reciprocatory member movable in the turret and connected to the tools, a chain of actuating elements connected to the reciprocatory member and capable of movement independently of one another, and latches for connecting elements of the chain to one another. 15
128. In a heel-attaching machine, a frame, a turret rotatable thereon, a group of operating sections pivoted upon the turret and each having a passage, a tool movable in each passage, a plunger mounted upon the turret and connected to the tools, a lever fulcrumed upon the frame, connections between the plunger and lever, portions of the connections being movable independently of one another, and yieldable latches carried by certain of the connecting portions and engaging other portions. 20
129. In a shoe machine, a rotatable turret, operating sections mounted upon the turret and each having a passage, a tool movable in each passage, a reciprocatory member movable in the turret and connected to the tools, a chain of actuating elements movable independently of one another and into engagement with one of which elements the reciprocatory member is carried by the turret in its rotation, and means arranged to retain the reciprocatory member in position to receive engagement of the actuating member when said plunger and actuating member are disengaged. 25
130. In a heel-attaching machine, a frame, a turret rotatable thereon, a group of operating sections pivoted upon the turret and each having a passage, a tool movable in each passage, a plunger mounted upon the turret and connected to the tools, an actuating lever fulcrumed upon the frame, a connecting lever fulcrumed upon the actuating lever, a connecting member pivoted upon the connecting lever for engagement with the plunger, and yieldable latches joining the levers to each other and the connecting lever to the connecting member. 30
131. In a heel-attaching machine, a frame, a turret rotatable thereon, a group of operating sections pivoted upon the turret and each having a passage, a tool movable in each passage, a plunger mounted upon the turret and connected to the tools, a yieldable latch connecting the plunger and turret, an actuating lever fulcrumed upon the frame, a connecting lever fulcrumed upon the actuating lever, a connecting member pivoted upon the connecting lever for engagement with the plunger, and yieldable latches joining the levers to each other and the connecting lever to the connecting member. 35
- joining the levers to each other and the connecting lever to the connecting member. 40
132. In a shoe machine, a work-support, operating sections arranged in pairs and each being yieldable from the work-support, and means interposed between a pair of sections and acting simultaneously upon both sections to retain them against yield. 45
133. In a shoe machine, a work-support, operating sections movable toward and from the support, a yieldable member for producing such movement, a locking member engaging the yieldable member, and a pressure member movable in engagement with the locking member. 50
134. In a shoe machine, a work-support, operating sections movable toward and from the support, a yieldable member for producing such movement, a locking member engaging the yieldable member, and a pressure member provided with an inclined wall movable into engagement with the locking member. 55
135. In a shoe machine, a work-support, operating sections arranged in pairs and each being yieldable from the work-support, a locking member acting upon each section, and a pressure member common to a pair of locking members. 60
136. In a shoe machine, a rotatable turret, operating sections yieldable upon the turret, and means carried by the turret for locking the sections against yield. 65
137. In a shoe machine, a rotatable turret, operating sections movable upon the turret, plungers yieldable upon the turret and engaging the sections, and means carried by the turret for locking the plungers against yield. 70
138. In a shoe machine, a rotatable turret, operating sections yieldable upon the turret and having passages, tools arranged to reciprocate in the passages, a plunger to which the tools are connected, means carried by the turret for locking the sections against yield, and releasing means for the locking means movable by the plunger. 75
139. In a shoe machine, a rotatable turret, operating sections yieldable upon the turret and having passages, tools arranged to reciprocate in the passages, a plunger to which the tools are connected, a locking member for each section, and a rod provided with a tapered end-portion engaging the locking member and connected to the plunger. 80
140. In a shoe machine, a rotatable turret, operating sections yieldable upon the turret and having passages, tools arranged to reciprocate in the passages, a plunger to which the tools are connected, a locking member for each section, a rod yieldably mounted upon the turret, and means carried by the plunger for engaging the rod. 85
141. In a shoe machine, a movable support, a plurality of operating mechanisms mounted upon the support, a work-holder in proximity to which the mechanisms are moved by the support, and means for causing the delivery of work by the holder to one only of the operating mechanisms. 90
142. In a shoe machine, a rotatable turret, a plurality of operating mechanisms mounted upon the turret, a work-holder in proximity to which the mechanisms are moved by the turret, and means operable by the turret for causing the delivery of work from the holder to an operating mechanism. 95
143. In a heel-attaching machine, a frame, a turret rotatable thereon, base-nailing mechanism and lift-nailing mechanism mounted upon the 100

5 turret, a work-support carried by the frame and into co-operation with which the nailing mechanisms travel in the rotation of the turret, a movable lift-holder associated with the turret, and means for operating the lift-holder to cause it to deliver to the lift-nailing mechanism.

10 144. In a shoe machine, a frame, a turret rotatable thereon, operating mechanism carried by the turret, a work-support co-operating with the turret, and a holder movable upon the frame only in predetermined position of the turret to present a work-piece between the support and operating mechanism.

15 145. In a shoe machine, a frame, a turret rotatable thereon, operating mechanism carried by the turret, a work-support co-operating with the turret, a holder normally situated above the operating field, and a parallel-motion connection joining the holder to the frame and arranged to 20 lower said holder to deliver a work-piece between the support and operating mechanism.

25 146. In a shoe machine, a frame, a turret rotatable thereon, operating mechanism carried by the turret, a work-support co-operating with the turret and movable toward and from the operating mechanism, and a holder movable upon the frame to present a work-piece between the support and operating mechanism and being yieldable in the direction of movement of the support.

30 147. In a shoe machine, a frame, a turret rotatable thereon, operating mechanism carried by the turret, a work-support co-operating with the turret and movable toward and from the operating mechanism, and a holder and mounting therefor movable upon the frame to present a work-piece between the support and operating mechanism, the holder being yieldably connected to its mounting.

40 148. In a heel-attaching machine, a frame, a jack, nailing mechanism carried by the frame, a heel-holder, a parallel-motion mounting pivoted to the frame and supporting the holder, and means acting upon the mounting to move the holder between the jack and nailing mechanism.

45 149. In a heel-attaching machine, a frame, a jack, nailing mechanism carried by the frame, a heel-holder, a parallel-motion mounting pivoted to the frame and supporting the holder, means acting upon the mounting to move the holder between the jack and mechanism, and a spring interposed between the holder and mounting.

55 150. In a heel-attaching machine, a frame, a support movable upon the frame and carrying mechanism for operating upon a heel, a heel-holder movable upon the frame, a slide arranged to reciprocate upon the frame and connected to the holder, and means for communicating movement of the support to the slide.

60 151. In a heel-attaching machine, a frame, a turret rotatable thereon and carrying mechanism for operating on a heel, a heel-holder pivotally mounted upon the frame, a slide arranged to reciprocate upon the frame, gearing connecting the slide and holder, and a cam movable with the turret and acting upon the slide.

70 152. In a nailing machine, nailing mechanism, means for moving a holding device to deliver nails to the nailing mechanism, means arranged to contain a plurality of the holding devices, and means operated by the machine for transferring a holding device from the containing means to the moving means.

75 153. In a nailing machine, nailing mechanism, means for moving a holding device to deliver nails to the nailing mechanism, means arranged

to contain a plurality of the holding devices, and means for transferring a holding device from the containing means to moving means after a predetermined number of operations of the nailing mechanism.

5 154. In a nailing machine, nailing mechanism, means for moving a holding device to deliver nails to the nailing mechanism, means arranged to contain a plurality of the holding devices in a stack resting one upon another, and means for 10 transferring holding devices from the top of the stack to the moving means.

15 155. In a nailing machine, nailing mechanism, means for moving a holding device to deliver nails to the nailing mechanism, means arranged to contain a plurality of the holding devices in a stack resting one upon another, means for transferring holding devices successively from the top of the stack to the moving means, and means for elevating the stack to present successive holding 20 devices to the transferring means.

25 156. In a nailing machine, nailing mechanism, means for moving a holding device to deliver nails to the nailing mechanism, means arranged to contain a plurality of the holding devices, means for transferring a holding device from the containing means to the moving means after a predetermined number of operations of the nailing mechanism, and means for simultaneously moving all the holding devices in the container.

30 157. In a nailing machine, the combination with nailing mechanism, of a stationary table arranged to support a block provided with nail-receiving openings, a feed-bar movable above the table and having means to engage the block upon the table, and means for advancing the bar 35 upon the table, and means for advancing the bar step by step, said bar being moved through one step for each operation of the nailing mechanism.

158. In a nailing machine, the combination 40 with nailing mechanism, of a stationary table arranged to support a block provided with nail-receiving openings, a feed-bar movable above the table and having means to engage the block upon the table, means for advancing the bar 45 step by step for successive operations of the nailing mechanism, a block-magazine associated with the table, and means for successively delivering blocks from the magazine to the table.

159. The combination with a table arranged to 50 support a nail-block, of feeding means for the block co-operating with the table, a block-containing cabinet situated below the table, and means for delivering blocks from the top of the cabinet to the table.

160. The combination with a stationary table arranged to support a nail-block, of a cover for the table, a block-feeding member guided in the cover, and means for moving the feeding member.

161. In a nailing machine, nailing mechanism, a support over which a nail-holding device is movable step by step for successive operations of the nailing mechanism, a movable device receiving nails from the holding device and delivering to the nailing mechanism, and means for moving the delivering device in definite time-relation to the movement of the holding device.

162. In a nailing machine, nailing mechanism, a support over which a nail-holding device is movable step by step for successive operations of the 70 nailing mechanism, a movable device receiving nails from the holding device and delivering to the nailing mechanism, and means for moving the delivering device for each operation of the nailing mechanism.

163. The combination with a table arranged to support a nail-block, of feeding means for the block co-operating with the table, and a discharge-roll rotatable below the table and receiving nails from the block. 5
164. The combination with a table arranged to support a nail-block, of feeding means for the block co-operating with the table, a discharge-roll rotatable below the table and receiving nails from the block, and means for turning the discharge-roll after each advance of the block. 10
165. In a nailing machine, nailing mechanism, a support for a nail-holding device, means for moving a holding device over the support to deliver nails in successive loads to the nailing mechanism, a container for a plurality of the holding devices, means for transferring holding devices from the container to the support, means for presenting the holding devices successively in the container for transfer, and means common to both for operating said transferring means and presenting means. 15
166. In a nailing machine, nailing mechanism, a support for a nail-holding device, means for moving a holding device over the support to deliver nails in successive loads to the nailing mechanism, a container for a plurality of the holding devices, means for transferring holding devices from the container to the support, means for presenting the holding devices successively in the container for transfer, and means common to both for operating said transferring means and presenting means after a predetermined number of operations of the nailing mechanism. 20
167. The combination with movable nail-holding devices, of means for moving a holding device to deliver nails therefrom, a container for a stack of the holding devices, a stack-carrying member movable in the container, a member movable to transfer holding devices from the stack to the moving means, and mechanism for simultaneously moving the stack-carrying member and transferring member. 25
168. The combination with a support for nail-holding devices, of means for moving a holding device over the support, a container for a stack of the holding devices, a stack-carrying member movable in the container, a member movable to transfer holding devices from the stack to the support, and mechanism for simultaneously moving the stack-carrying member to present to a holding device for transfer and moving the transferring member to its active position. 30
169. The combination with a support for nail-holding devices, of means for moving a holding device over the support, a container for a stack of the holding devices, a stack-carrying member movable in the container, a member movable to transfer holding devices from the stack to the support, a spring arranged to produce the active movement of the transferring member, and means for reversing the movement and tensioning the spring. 35
170. The combination with a support for nail-holding devices, of means for moving a holding device over the support, a container for a plurality of the holding devices, a member for transferring devices from the container to the support, and a spring arranged to operate said transfer-ring member. 40
171. The combination with a support for nail-holding devices, of means for moving a holding device over the support, a container for a plurality of the holding devices, a member for transferring devices from the container to the support, and a spring arranged to produce the transfer-ring movement of the member. 45
172. The combination with a support for nail-holding devices, of means for moving a holding device over the support, a container for a plurality of the holding devices, a member for transferring devices from the container to the support, a spring arranged to produce the transfer-ring movement of the member, and means for latching the member in position against the force of the spring. 50
173. The combination with a table arranged to support a block provided with nail-holding openings, of a block-magazine, a movable platform arranged to carry a stack of blocks in the magazine, a block-transferring finger movable between the magazine and table, and a lever acting to move both the finger and the platform. 55
174. In a nailing machine, the combination with nailing mechanism and operating means therefor, of a table arranged to support a block provided with nail-holding openings, a block-magazine, a movable platform arranged to carry a stack of blocks in the magazine, a block-transferring finger movable between the magazine and table, a lever acting to move both the finger and the platform, connections to the operating mechanism for moving the lever in one direction, and a spring arranged to move the lever in the opposite direction. 60
175. In a nailing machine, the combination with nailing mechanism and operating means therefor, of a table arranged to support a block provided with nail-holding openings, a block-magazine, a movable platform arranged to carry a stack of blocks in the magazine, a block-transferring finger movable between the magazine and table, a lever acting to move both the finger and the platform, connections to the operating mechanism for moving the lever to elevate the platform and retract the finger, and a spring arranged to move the lever in the opposite direction. 65
176. The combination with a table arranged to support a block provided with nail-holding openings, of a block-magazine, a block-transferring member movable between the magazine and table, and a latch normally maintaining said member against movement. 70
177. The combination with a table arranged to support a block provided with nail-holding openings, of a block-magazine, a platform arranged to carry a stack of blocks in the magazine, an operating lever fulcrumed adjacent to the magazine, a rod extending transversely of the lever, and a plurality of block-engaging fingers pivoted upon the rod. 75
178. The combination with a table arranged to support a block provided with nail-holding openings, of a block-magazine, a platform arranged to carry a stack of blocks in the magazine, an operating lever fulcrumed adjacent to the magazine, a rod extending transversely of the lever, a plurality of block-engaging fingers pivoted upon the rod and each provided with a recess, and a latch arranged to occupy the recesses. 80
179. The combination with a support for nail-holding devices, of means for moving a holding device over the support, a container for a stack of the holding devices, a stack-carrying member movable in the container, a member movable to transfer holding devices from the stack to the support, and means for cushioning the movement of the member. 85
180. The combination with a support for nail- 75

holding devices, of means for moving a holding device over the support, a container for a plurality of the holding devices, a member for transferring devices from the container to the support, 5 a spring arranged to operate said transferring member, and means for cushioning the movement of the member under the influence of the spring. 181. The combination with a table arranged to support a block provided with nail-holding openings, of a block-magazine, a platform arranged to carry a stack of blocks in the magazine, an operating lever, a block-transferring member movable by the lever between the magazine and table, and means connected to the lever for cushioning 15 the movement of the transferring member.

182. The combination with a table arranged to support a block provided with nail-holding openings, of a block-magazine, a platform arranged to carry a stack of blocks in the magazine, an 20 operating lever, a spring for moving the lever, a block-transferring member pivoted upon the lever and movable between the magazine and table, and a dash-pot connected to the lever.

183. The combination with a support for nail-holding devices, of means for moving a holding device over the support, a container for a plurality of holding devices, a member for transferring devices from the container to the support, a 25 spring arranged to move the transferring member in one direction, a latch for retaining the member against the force of the spring, an operating member, and connections to the member for moving the transferring member to its latched position, there being means for preventing the 30 striking of the connections by the operating member when the transferring member is latched.

184. The combination with a table arranged to support a block provided with nail-holding 40 openings, of a block-magazine, a block-transferring member movable between the magazine and table, and a latch normally maintaining said member against movement, said latch having an inclined surface into engagement with which 45 the member is movable.

185. The combination with a table arranged to support a block provided with nail-holding openings, of a block-magazine, a block-transferring member movable between the magazine and table 50 and provided with a recess, and a latch entering the recess to normally maintain the member against movement, said latch being of substantially less width than the recess and having an inclined surface engaged by the member.

186. The combination with a table arranged to support a block provided with nail-holding openings, of a block-magazine, a platform arranged to carry a stack of blocks in the magazine, an operating lever fulcrumed adjacent to the 55 magazine, a cam for moving the lever, a block-transferring member carried by the lever, a latch for the member, and a spring normally maintaining the lever in engagement with the latch, said latch being provided with means for holding the lever out of striking engagement with the cam.

187. The combination with a stationary support for a nail-holding device provided with a nail-retaining member, there being in the support a depression to receive the retaining member, of means for advancing the holding device over the support away from the depression, leaving the retaining member in said depression. 70

188. The combination with a table arranged 75 to support a block provided with nail-receiving

openings and a shutter, there being in the table a depression to receive the shutter, of means for advancing the block over the table, leaving the shutter in the depression.

189. The combination with a support for a nail-holding device, there being openings from the support through which nails are discharged from the holding device, of means for feeding the holding device over the support for the discharge of the nails, and means for advancing the holding device upon the support in a direction inclined to the direction of feed of the device for the discharge of the nails. 5 10

190. The combination with a support for a nail-holding device, there being openings from the support through which nails are discharged from the holding device, of means for feeding the holding device over the support for the discharge of the nails, and means for advancing the holding device upon the support first in a direction at right angles to the direction of feed and then in 20 a direction inclined thereto. 15

191. The combination with a support for a nail-holding device, said device being provided with nail-holding openings and a nail-retaining shutter, the support having shutter-engaging means, of a delivering device associated with the support, means for feeding the holding device over the support for co-operation with the delivering device, means for advancing the holding 25 device upon the support into cooperation with the shutter-engaging means and with the feeding means, and means for thereafter changing the direction of advance of the holding device to align the nail-holding openings with the delivering 30 device. 35

192. The combination with a table for supporting a nail-block provided with a series of sets of nail-holding openings, of a discharge-roll having openings, means for feeding the block over the table to present the sets of openings successively to the roll-openings, and means for advancing the block into co-operation with the feeding means and with the first set of block-openings registering with the roll-openings. 40 45

193. The combination with a table for supporting a nail-block provided with a series of sets of nail-holding openings, of a discharge-roll having openings arranged in a series longitudinally of its axis, means for feeding the block over the table to present the sets of openings successively to the roll-openings, and means for advancing the block longitudinally of the axis of the roll and into co-operation with the feeding means and transversely of the axis to bring the first set of block-openings into registration with the roll-openings. 50 55

194. The combination with a table for supporting a nail-block provided with a series of sets of nail-holding openings, of a discharge-roll having openings, means for feeding the block over the table to present the sets of openings successively to the roll-openings, means for advancing the block into co-operation with the feeding means and with the first set of block-openings registering with the roll-openings, and means for actuating the feeding means while the advance of the block into co-operation with it is still in progress. 60 65

195. The combination with a table provided with a depression and arranged to support a nail-block provided with a series of sets of nail-holding openings and with a sliding nail-retaining shutter, of a discharge-roll co-operating with 70 75

- the table and having openings arranged in a series longitudinally of its axis, and means arranged to move the nail-block upon the table first in a direction longitudinally of the series of roll-openings to introduce the shutter into the depression and then transversely of the series of openings to bring the first set of block openings freed from the shutter into registration with the roll-openings. 5
106. The combination with a table arranged to support a nail-block provided with nail-holding openings, of means for advancing the block upon the table, and a movable member with which the forward portion of the block contacts in its movement, there being means made effective in such movement to shift the block at an angle to its advance upon the table. 10
197. The combination with a table arranged to support a nail-block provided with nail-holding openings, of means for advancing the block upon the table, and a lever having an arm extending into the path of the block for contact with one edge, another arm of the lever being arranged to act upon an adjacent edge of the block. 15
198. The combination with a table arranged to support a nail-block provided with nail-holding openings, of means for advancing the block upon the table, a feeding member engaging the block, and a lever fulcrumed at the table and having an arm extending into the path of the block, another arm of the lever being arranged to contact with the feeding member to move the block. 20
199. The combination with a table arranged to support a nail-block provided with nail-holding openings, of means for advancing the block upon the table, a roll co-operating with the table and provided with discharge-openings, means for advancing the block upon the table with its openings clear of the roll-openings, and a member arranged for contact with the block to move it during its advance to bring its openings into registration with the roll-openings. 25
200. The combination with a table arranged to support a nail-block provided with nail-holding openings, of means for advancing the block upon the table, a roll co-operating with the table and provided with discharge-openings, means for advancing the block upon the table with its openings clear of the roll-openings, and a lever having an arm with which the forward edge of the block contacts and a second arm movable in co-operation with an adjacent edge of the block to carry the block toward the roll. 30
201. The combination with a table arranged to support a nail-block provided with nail-holding openings, of means for advancing the block upon the table, a roll co-operating with the table and provided with discharge-openings, a feed-bar co-operating with the table, means for advancing the block upon the table into engagement with the feed-bar with its openings clear of the roll-openings, and a lever having an arm with which the forward edge of the block contacts and a second arm movable against the feed-bar to carry the block with its openings in registration with the roll-openings. 35
202. In a nailing machine, a plurality of movable nailing mechanisms, means for moving the nailing mechanisms successively to operating position, a nail-holder movable to deliver successive sets of nails, and means for moving the holder once for the movement of plural nailing mechanisms into operating position. 40
203. In a nailing machine, a rotatable turret, a plurality of nailing mechanisms mounted upon the turret and movable thereby to operating position, a nail-holder movable to deliver successive loads of nails to the nailing mechanisms, and means for moving the holder once for each rotation of the turret. 45
204. In a nailing machine, nailing mechanism, a support for a nail-holding device, a member for feeding the holding device over the support, means for moving the member step by step in one direction to deliver nails to the nailing mechanism in successive loads, and means acting upon a predetermined number of operations of the nailing mechanism for returning the member to its initial position. 50
205. In a nailing machine, a rotatable turret, a plurality of nailing mechanisms mounted upon the turret and movable thereby to operating position, a block provided with sets of nail-holding openings and being movable to present the sets of openings successively for the delivery of nails to the nailing mechanisms, and means for advancing the block a step for each rotation of the turret. 55
206. The combination with a stationary table arranged to support a block provided with nail-holding openings, of a rack-bar extending above and separably engaging the block presented to it upon the table, a pawl movable in engagement with the rack bar, and means for actuating the pawl. 60
207. In a nailing machine, a rotatable turret, nailing mechanism carried thereby, a table arranged to support a block provided with nail-holding openings, a rack-bar for moving the block to deliver nails to the nailing mechanism, a pawl movable in engagement with the rack-bar, and connections to the turret for actuating the pawl. 65
208. The combination with a table arranged to support a block provided with nail-holding openings, of a cover upon the table above the block, a rack-bar guided by the cover and engaging the block, a pawl movable in engagement with the rack-bar, and means for actuating the pawl. 70
209. The combination with a table arranged to support a block provided with nail-holding openings, of a cover upon the table above the block, a rack-bar guided by the cover and engaging the block, a pawl movable in engagement with the rack-bar, means for actuating the pawl, and a retaining detent pivoted upon the cover and engaging the rack-bar. 75
210. The combination with a table arranged to support a block provided with nail-holding openings, of means for feeding forward the block to deliver nails therefrom upon each advance, and automatic means for returning the block to its initial position. 80
211. The combination with a table arranged to support a block provided with nail-holding openings, of means for feeding forward the block step by step to deliver nails therefrom upon each advance, means for temporarily retaining the block against reverse movement at the termination of each step, and means for applying to the block a force tending constantly to return it to its initial position. 85
212. The combination with a table arranged to support a block provided with nail-holding openings, of a feeding member separably engaging the block, and a weight joined to the feeding member and leaving the block free for separation. 90
213. In a nailing machine, a rotatable turret, 95

nailing mechanism carried thereby, a table arranged to support a block provided with nail-holding openings, a rack-bar for moving the block to deliver nails to the nailing mechanism, 5 a pawl movable in engagement with the rack-bar, connections to the turret for actuating the pawl, and connections to the rack-bar to return it to its initial position.

214. The combination with a table arranged to support a block provided with nail-holding openings, of a member engaging the block to feed it over the table for the delivery of the nails, means for advancing the member step by step, a retaining member for the feeding member, and means 10 controlled by the feeding member for releasing said feeding member from the retaining member.

215. The combination with a table arranged to support a block provided with nail-holding openings, of a member engaging the block to feed it over the table for the delivery of the nails, means for advancing the member step by step, a retaining member for the feeding member, means for returning the member to its initial position after such delivery, and means for moving the 15 retaining member out of engagement with the feeding member and holding it during the return-movement.

216. The combination with a table arranged to support a block provided with nail-holding openings, of a member engaging the block to feed it over the table for the delivery of the nails, means for advancing the member step by step, a retaining member for the feeding member, and a member movable by the feeding member in engagement with the retaining member to release the feeding member and also movable by the feeding member to release the retaining member.

217. The combination with a table arranged to support a block provided with nail-holding openings, of a member engaging the block to feed it over the table for the delivery of the nails, means for advancing the member step by step, a retaining member for the feeding member, and a slide cooperating with the retaining member and movable by the feeding member into contact with the retaining member.

218. The combination with a table arranged to support a block provided with nail-holding openings, of a member engaging the block to feed it over the table for the delivery of the nails, means for advancing the member step by step and for returning it to its initial position, a retaining member for the feeding member, and a slide cooperating with the retaining member and receiving contact of the feeding member at the opposite extremes of movement to change the relation of the retaining member to said feeding member.

219. The combination with a table arranged to support a block provided with nail-holding openings, of a rack-bar co-operating with the block, an oscillatory pawl engaging the rack-bar to impart to the block a nail-delivering movement, means for returning the rack-bar to its initial position, a detent engaging the rack-bar, and a slide movable into engagement with the detent to disengage it from the rack-bar.

220. The combination with a table arranged to support a block provided with nail-holding openings, of a rack-bar co-operating with the block, an oscillatory pawl engaging the rack-bar to impart to the block a nail-delivering movement, means for returning the rack-bar to its initial position, a detent engaging the rack-bar, and a slide movable into engagement with the detent to disengage it from the rack-bar, there

being projections at opposite extremities of the rack-bar engaging the slide to effect its movement.

221. The combination with a movable nail-holding device, of a member movable to feed the holding device and deliver nails therefrom, a container for a plurality of holding devices, means for transferring holding devices from the container into co-operation with the feeding member, and means actuated by the feeding member at one extreme of its movement for initiating the action of the transferring means. 5

222. The combination with a support for a nail-holding device, of a reciprocating member for feeding the holding device over the support 10 to deliver nails, a container for a plurality of holding devices, means for transferring holding devices from the container to the support, and means actuated by the feeding member at one extreme of its movement for initiating the action 15 of the transferring means.

223. The combination with a movable nail-holding device, of a reciprocating member for feeding the holding device to deliver nails, a container for a plurality of holding devices, means 20 for transferring holding devices from the container into co-operation with the feeding member, and means actuated by the feeding member at one extreme of its movement for initiating the action 25 of the transferring means and changing the direction of travel of the holding device being transferred.

224. The combination with a block provided with nail-holding openings, of a member arranged to feed the block step by step to deliver 30 nails therefrom, a magazine, a member movable to transfer blocks from the magazine into co-operation with the feeding member, a latch for the member, and means actuated by the feeding member for releasing the latch. 40

225. The combination with a table arranged to support a block provided with nail-holding openings, of a member arranged to feed the block step by step over the table for the delivery of nails therefrom and then to return to its initial position, a magazine situated adjacent to the table, a member movable to transfer blocks from the magazine to the table, a latch for the member, and a lever actuated upon the return of the feeding member to release the latch. 45

226. The combination with a table arranged to support a block provided with nail-holding openings, of a member arranged to feed the block step by step over the table for the delivery of nails therefrom and then to return to its initial position, a magazine situated adjacent to the table, a member movable to transfer blocks from the magazine to the table, a latch for the member, a lever operable by the feeding member upon its return, and a lever movable by the first-mentioned lever and contacting with the latch. 55

227. In a nailing machine, nailing mechanism, a nail-holding device, a member for feeding the holding member, means for moving the member step by step in one direction to deliver nails from the holding device to the nailing mechanism in successive loads, means actuated upon a predetermined number of operations of the nailing mechanism for returning the member to its initial position, a container for a plurality of holding devices, means for transferring a holding device from the container into co-operation with the feeding member, and means actuated upon the return of the feeding member for initiating the action 65 of the transferring means. 70

228. The combination with a nail-holding device, of a member for feeding the holding device to deliver nails therefrom, a container for a plurality of holding devices, and means for transferring the holding devices successively from the container into co-operation with the feeding member, each device in its feeding movement being arranged to contact with a previously transferred holding device and displace it from its delivering relation.
229. The combination with a device provided with nail-holding openings and with a nail-retaining slide, of means for feeding the holding device while the slide is retained against movement to deliver nails from the device, a container for a plurality of the holding devices with their slides, and means for transferring the holding devices successively from the container into co-operation with the feeding means, the slide of each device during transfer being arranged to contact with a previously transferred slide to displace it from the support and each device in its feeding movement being arranged to contact with the holding device of said displaced slide to eject it.
230. The combination with a table arranged to support a block provided with nail-holding openings, of a rack-bar engaging the block upon the table, means for moving the bar to feed the block over the table and deliver nails from the openings and for returning the bar to its initial position, a block magazine associated with the table, and means for transferring blocks from the magazine to the returned bar, each block contacting in its feed with the block previously fed.
231. The combination with a table arranged to support a block provided with nail-holding openings and with a shutter movable upon the block to free the openings for nail-delivery, the table having a depression to receive and retain the shutter, of a rack-bar engaging the block upon the table, means for moving the bar to feed the block over the table and deliver nails from the openings and for returning the bar to its initial position, a block-magazine associated with the table, and means for transferring blocks from the magazine to the returned bar, each shutter during the transfer of its block contacting with that of the block previously transferred and each block in its feed contacting with the previously transferred block.
232. In a nailing machine, a plurality of nailing mechanisms, a nail-holder arranged to supply nails to plural mechanisms, and a movable nail-delivering device interposed between the holder and nailing mechanisms and provided with groups of delivery-openings, each group corresponding in number to the nails to be supplied to a particular mechanism.
233. In a nailing machine, a plurality of nailing mechanisms, a nail-holder arranged to supply nails to plural mechanisms, a rotatable discharge-roll interposed between the holder and nailing mechanisms and provided with groups of delivery-openings, and means for rotating the roll to bring groups of openings successively into delivering relation.
234. In a nailing machine, a plurality of nailing mechanisms, a nail-holder arranged to supply nails to plural mechanisms, a rotatable discharge-roll interposed between the holder and nailing mechanisms and provided with groups of delivery-openings, and means for rotating the roll through 180° to bring groups of openings successively into delivering relation and completing

the rotation of the rolls to render the openings successively effective to deliver in the opposite direction.

235. In a nailing machine, a rotatable turret, a plurality of nailing mechanisms movable by the turret into operating position, a nail-holder arranged to supply nails to the mechanisms, and a movable member provided with groups of openings corresponding to the nailing mechanisms and connecting the holder and the different mechanisms in different positions of the member.

236. In a nailing machine, a rotatable turret, a plurality of nailing mechanisms movable by the turret into operating position, a nail-holder arranged to supply nails to the mechanisms, and a rotatable roll provided with a group of openings for each nailing mechanism and successively connecting the holder and mechanisms in the rotation of the roll.

237. In a nailing machine, a rotatable turret, a plurality of nailing mechanisms movable by the turret to operating position, a nail-block provided with sets of nail-holding openings, a discharge-roll provided with a group of openings corresponding to each nailing mechanism, and means for feeding the block to bring each set of its openings into co-operation with the groups of roll-openings.

238. In a nailing machine, a rotatable turret, a plurality of nailing mechanisms movable by the turret to operating position, a nail-block provided with sets of nail-holding openings, a discharge-roll provided with a group of openings corresponding to each nailing mechanism, and means for rotating the discharge-roll to bring its groups of openings successively into registration with a set of block-openings.

239. In a nailing machine, a rotatable turret, a plurality of nailing mechanisms movable by the turret to operating position, a nail-block provided with sets of nail-holding openings, a discharge-roll provided with a group of openings corresponding to each nailing mechanism, means for rotating the discharge-roll to bring its groups of openings successively into registration with a set of block-openings, and means for feeding the block to bring each set of openings into co-operation with the groups of roll-openings.

240. The combination with a block provided with a series of sets of nail-holding openings, of a delivery device provided with openings movable into registration with a set of block-openings, and means for feeding the block to present the sets of openings successively to the delivery device.

241. The combination with a block provided with sets of nail-holding openings, of a rotatable discharge-roll provided with groups of openings separated from one another angularly about the roll, and means for rotating the roll to bring the groups of openings successively into registration with a set of block-openings.

242. The combination with a table arranged to support a block provided with a series of sets of nail-holding openings, of a rotatable discharge-roll provided with groups of openings separated from one another angularly about the roll, and means for feeding the block to present the sets of openings successively to the discharge roll.

243. The combination with a block provided with sets of nail-holding openings, of a rotatable discharge-roll provided with groups of openings separated from one another angularly about the roll, means for rotating the roll, and means for

producing alinement between the successive groups of nail-openings and a set of block-openings.

244. The combination with a table arranged to support a block provided with sets of nail-holding openings, of a rotatable discharge-roll provided

with groups of openings separated from one another angularly about the roll, ratchet mechanism for rotating the roll, a star-wheel fixed to the roll, and a retaining member engaging the star-wheel.

ROBERT H. LAWSON.
